UNITED STATES PATENT OFFICE.

CLINTON ALVORD, OF WORCESTER, MASSACHUSETTS.

COLOR-PRINTING MECHANISM.

1,383,589.

Specification of Letters Patent. Patented July 5, 1921.

Application filed August 5, 1920. Serial No. 401,324.

To all whom it may concern:

Be it known that I, CLINTON ALVORD, a citizen of the United States, residing at Worcester, in the county of Worcester and

5 State of Massachusetts, have invented a new and useful Color-Printing Mechanism, of which the following is a specification.

My invention relates to improvements in color printing machines for coloring warp 10 yarns for tapestry or velvet carpets. This invention is an improvement on and an addition to that shown in my application filed August 20, 1919, and numbered 318,716 of the series of 1915, in which I show as one embodiment of my invention, a machine for automatically positioning the yarn cylinder and controlling the action of the color car while all the stripes of one color called for on the design are being printed and in which 15 the dye is then changed by hand from one to the next color. The present application shows my selective automatic mechanism for changing the colors after they have been used.

20 25 The main object of my invention is to provide an automatic machine for selectively substituting a new color for an old one which has colored the yarn at all spots demanded by the design, and so on *seriatim* until the 30 yarn has been automatically dyed with as many colors as the pattern requires.

35 A further object of my invention is to provide a suitable magazine for holding the color printing elements with their color dyes and reservoirs containing additional dye, and also to provide automatic means for actuating and positioning the magazine.

40 Another object of my invention is to position the color-printing mechanism while a change is made to a new color.

Another object of my invention is to keep 45 the yarn support from moving during the time of color change.

Another object of my invention is to provide automatic devices for wiping the scrapers when a new color is placed in the color-printing mechanism.

50 Another object of my invention is to position a color supply container and transfer color from it at predetermined intervals to the color printing mechanism.

Still a further object of my invention is to prevent the color printing mechanism

from contacting with and making color impression upon the yarn, at certain predetermined intervals, while still functioning in other particulars. 55

Having thus broadly stated the main objects of my invention I will disclose one good form in which I expect to apply it. In this 60 case the yarn is shown as being wound in coils on the conventional printing drum and then striped transversely by a color roller.

With the above and other objects in view my invention consists in the construction, 65 arrangement and details of construction disclosed in the drawings and specification and then more particularly pointed out in the appended claims.

In the drawings wherein similar reference 70 characters designate similar parts throughout the respective views:

Figure 1 is a front elevation of the index end of my automatic printing drum;

Fig. 2 is a general plan view showing the 75 location and arrangement of the various parts of the mechanisms, the cylinder being broken away;

Fig. 3 is a left hand side elevation illustrating the main parts of my invention; 80

- Fig. 36 is a fragmentary left hand side elevation showing the color change mechanism;
- Fig. 37 is a perspective assembly of the automatic secondary color-car control. The frame of the printing drum and supporting brackets are omitted for the sake of clearness;
- Fig. 37^A is a perspective view showing the intersection between the feeler and accessories;
- Fig. 38 is a perspective detail of the sliding tooth gears;
- Fig. 39 is an enlarged left hand side elevation of the color-car, its positioner, etc.,
- Fig. 40 is a plan of Fig. 39; and
- Fig. 41 is a partial side elevation showing means for locking down the color car.
- In the drawings which are merely illustrative of my mechanism all the parts of my invention are disclosed.
- My device is made in this particular instance as an attachment to the standard manually operated printing drum and the various brackets and bearing attach to and are supported by the regular drum frame of the machines in common use in this country and England in which will be found the usual yarn cylinder, means for winding the yarn thereonto, color-car and the operating means therefor, etc., and the use of my invention makes such a machine an automatic one. 1 is the yarn cylinder turning freely on its axis when driven by the regular pulley 2, and associated gearing. Various skeins of yarn 3 are on spools 4 and are respectively mounted freely on spindles 5. The yarn 3 passes upward from the spools 4 through the yarn guides 6 to the cylinder and the end of each skein of yarn is made fast thereonto so that when the cylinder is revolved the various skeins will be wound thereupon preparatory to being colored. The guides 6 are attached to the bar 7, which by means of the rack 8 in mesh with the gear 9, is caused to move slowly across the face of the cylinder by suitable gearing as in usual practice so as to lay the bights or coils of yarn side by side, one deep, over the surface thereof, the terminal end of one skein meeting the initial point of its neighbor skein. A certain degree of tension is imparted to the yarn by means of the friction pads 10 which are pressed against the yarn on the spools 4 by the action of weights 11, and thus the yarn is laid smoothly and somewhat snugly on the cylinder so as to present a suitable surface for the coloring operation. The rear ends of the skeins are attached to the cylinder as soon as the winding is completed, as in regular practice.
- The cylinder 1 is equipped with an internal annular gear 12, made fast thereto by the stands 13 (Figs. 27 and 1) and a gear 14 fast on shaft 15 meshes with the teeth of gear 12. Shaft 15 turns freely in bearing 15' (Fig. 2) and in the manually operated printing drums in common use a hand wheel 14' is made fast to the other end of shaft 15 so that the operative can place the yarn cylinder 1 in any desired annular position by turning the hand wheel and he is kept constantly employed doing this and operating the printing mechanism.
- I substitute a jacquard machine with its perforated strip in place of the operative and will now describe my new mechanism for the selective automatic positioning of the yarn cylinder 1, the control of the printing of the yarn, the placing of the different colors, etc.
- The jacquard is indicated by the perforated strip 16 which feeds over the cylinder 17 in the conventional manner, and acts on

the vertical needles 18 which control the action of the jacquard hooks 19 that pass through loops in the needles as is the usual jacquard practice. The turned up end 20 of the hooks 19 are acted upon by the griffe 21 (Fig. 30). A hole in strip 16 will allow the corresponding needle 18 to remain down, but a blank spot on the strip will raise that particular needle, when the cylinder 17 is raised to indicate the needles, and its respective hook 19 is therefore raised so that the end 21 will be elevated up over the griffe 21. The griffe makes an operative stroke to the left while the jacquard cylinder 17 is "up" and upon contacting the ends 20 of the hooks that have not been lifted, the griffe continues to move (Fig. 30) and forces toward the left all those hooks 19 that have not been raised above the griffe 21, while the hooks that have been raised like 19' will not be moved by the griffe. The bar 22 which is attached to the griffe is positioned to act on the left hand side of the turned-up ends 20 of the hooks 19 and draws all moved hooks toward the right when the griffe makes its retrograde movement and thus the hooks 19 are all lined up once more ready for another indication as called for by the design to be printed and which is represented by the holes in the strip 16. The left hand or inner ends of the hooks 19 are passed through holes 23 in a plate 24 which holes are arranged in a circle of preferably forty-eight holes. Plate 24 is attached to the main frame of the printing drum and its center is machined to receive a pin or stud 25 held in place by the set screw 26. Upon this stud 25 is freely journaled my index wheel 27 which controls the position of the yarn cylinder 1 and the action of the printing mechanism. Index wheel 27 is provided on its periphery with preferably forty-eight ratchet teeth 28 and for each tooth there is also drilled a hole 29 placed mid-way of two adjacent teeth and which is the seat of a slidably projectable pin 30. Each pin has a head 31 suitable to be acted upon by the ends 32 of the jacquard hooks 19 (Fig. 19). The hooks 19 act when the index wheel 27 is positioned with the pins 30 in line with the holes 23 in the plate 24 and the impact and subsequent movement of the ends 32 of the hooks 19 against the heads 31 of the pins 30 project the pins through the holes 29 until the shoulder 33 of each pin thus moved contacts against the face 34 of the index wheel 27 while the end 35 of each moving pin is protruded about three-eighths of an inch beyond the face 36 of the index wheel. Thus for each projectable pin 30 there is a corresponding hole 29, ratchet tooth 28, jacquard hook 19, and needle 18. The ends 32 of the hooks 19 are arranged in a circle, so as to register with the pins in the index wheel, but the turned up ends 20 come down to a straight line as shown in Fig. 31.

Index wheel 27 is provided with an extended hub 37 upon which is fastened the spiral gear 38 which meshes with spiral gear 39 fast on hand wheel shaft 15, (Fig. 27). Thus a rotating movement imparted to index wheel 27 will move yarn cylinder 1, the motion being transmitted through the meshed spirals and the gears 14 and 12.

I will now describe how automatic motion is imparted to my index wheel 27 which acts like and takes the place of the usual operative and hand wheel. Index pawl lever 40 is freely mounted on the extended hub 37 of the index wheel and next to the ratchet 28 and at its outer end is freely attached the pawl 41 on the fulcrum pin 42 being designed to work with the ratchet teeth 28 of the index wheel. The spring 43 causes the pawl to click sharply into the teeth of the ratchet. The pawl lever 40 is provided with the rib 44 which is located opposite to the circle of pins in the index wheel and extends close up to the face 36 through which the pins 30 are projected by the jacquard hooks back of the rib 44, and the protruding pins act in turn as checks against the rearward movement of the pawl lever and when rib 44 is in contact with a pin the pawl clicks properly into the corresponding ratchet tooth. The motion of the pawl lever 40 forwardly about the hub 37 is directly limited by the dead stop 45 and indirectly rearwardly by the dead stop 46, the total circular movement being a little more than one half a circle, or about twenty-four and three-quarters ratchet teeth.

The pawl lever 40 is retracted by the pull of the band 47 attached to the hub of pawl lever 40 at 48 (Fig. 28) for the weight 49 is attached to the other end of the band, hence after an operative stroke the pawl is automatically retracted until arrested indirectly by dead stop 46, or directly by a protruded pin 30. The working stroke of the pawl 41 is caused by the pusher finger 50 which contacts on the boss 51 of the pawl lever 40 and urges the lever forward until checked by the dead stop 45 as clearly shown in Figs. 28 and 29. The pusher finger 50 is attached to the arm 52 which has the hub 53 (Fig. 29) journaled freely on the hub 37 of the index wheel. Spur gear 54 is firmly attached to pusher hub 53 and meshes with rack 55, the rod head 55' of which is pivoted on the crank stud 56 of crank arm 57' which is keyed fast to shaft 57 revolving in suitable bearings and which receives a fast and slow motion from the constantly rotating shaft 58 by means of the sector gears 59 and 60 keyed respectively to shafts 58 and 57. Shaft 58 is a constantly rotating shaft driven independently of the index and which

operates the index. These sector gears are so timed as to make the crank stud 56 receive its working stroke in slow time while its return stroke is made in almost one-half 5 the same period of time. It oscillates once each way for one revolution of the crank arm 56. The crank 57' revolves twice to one revolution of the constantly revolving shaft 58. The sweep of the pusher finger 10 shaft 58. The sweep of the pusher finger 50 around its axis, which of course coincides with the axis of the index wheel 27, is a little greater than the full sweep of the pawl lever 40. When the rib 44 of the lever 40 is in contact with a protruding pin 30 the pusher 15 will make a partial idle forward stroke until it comes in contact with lug 51 and will then proceed to drive the index pawl lever forward to the dead stop 45. The index wheel is always rotated forwardly by a movement 20 of the pawl 41, and the degree of angularity of this movement is determined by the distance the pawl 41 moves backward until checked. The shortest operative stroke of the pawl covers a distance equal to but 25 one tooth of the ratchet 27, and the greatest stroke includes twenty-four teeth of the ratchet; and the ratio of the communicating gears is such that a move of one ratchet tooth causes a corresponding movement in 30 the yarn cylinder equal to the passage of a color stripe, therefore my index wheel will cause the yarn cylinder to be turned tooth by tooth, or in skips up to twenty-four teeth, just as does the hand of the operative upon 35 the hand wheel of the ordinary machine. My index wheel takes the place of the operative and his hand wheel, turning the yarn cylinder in the proper time, and holding it at rest for the requisite periods just as does the 40 operative in the well known hand controlled machine.

Spiral gear 38 is equipped with a brake drum 61 (Fig. 1) over which can pass a suitable conventional friction band to cause 45 sufficient drag to prevent the index wheel from running away from the pawl 41 and assures that the cylinder comes to rest at the proper angular spacings.

I will now describe how the rib 44 of the 50 index pawl lever 40 on its retraction gets past the jacquard protruded pin that checked the rib. There is an imaginary line passing through the center of the axis of the index wheel called the zero line and this 55 line is marked X—X on Fig. 27. The center of the pivot pin 42 of the index pawl 41 coincides with the zero position or X—X line when the pawl lever is checked by the front dead stop 45, as illustrated by Fig. 27. 60 Fast to plate 24 is the retracting cam 63 (Figs. 18 and 19) which is so located near line X—X that the head 31 of any jacquard protruded pin 30 will contact this cam just after the index wheel passes the location of 65 the end 32 of the jacquard hook 19 that is

located immediately back from the zero point and the continued forward movement of the index wheel for the single space up to zero will cause the contacting pin to be cammed back, or retracted, into inoperative 70 position as regards the index pawl lever.

The rib 44 of pawl lever 40 is now free of the pin immediately back of it, and against which it had stopped, and the weight 48 retracts the pawl lever and it follows the re- 75 treating pusher until rib 44 comes in contact with another protruded pin, or until the lever is checked by the rear dead stop 46. Thus the jacquard projected pins 30 are retracted whenever they pass the zero point, 80 so that one complete rotation of the index wheel will cause every projected pin to be retracted by the cam 63. In the circle of pins 30 on the disk is a spring actuated pin 64 which is projected by the flat spring 65, 85 and this pin is likewise retracted by the cam 63. As it is protruded by the spring it is called the "spring pin" and as soon as it passes cam 63 it is forced out beyond the face 36 of the index wheel by action of the 90 spring 64 and consequently the rib 44 always comes in contact with this "spring pin" and the index pawl lever always stops against it. Thus whenever the pawl lever is checked rearwardly by the "spring pin" the 95 pusher will upon its next operative stroke bring the spring pin to the zero point.

The jacquard is timed to indicate and pro- 100 trude the pins 30 at this point; *i.e.* the spring pin 64 is retracted being at zero and its head 31 is resting on the cam 63 and in this position all the other forty-seven pins 30 in the circle are each located opposite the working end 32 of a jacquard hook 19.

Spring pin 64 is not projected by a jac- 105 quard hook for its office is to assure that the index wheel always stops with the spring pin at zero so that the pins in the wheel can be "set up" anew by the jacquard. Thus the predetermined lay-out of the perfora- 110 tions in the jacquard strip 16 will automatically determine the annular movements of the yarn cylinder 1.

I will now describe the method of printing the yarn and show how my devices automatically control the coloring of the yarn. 115

As shown in Fig. 14 a hub 65 is splined fast on shaft 58 so as to rotate therewith. Adapted to turn about and upon hub 65 is the hub 66 carrying the crank arm 67. The 120 shaft 58 receives its motion from pulley 2 shown in Figs. 1 and 3 through the pinion gear 69 meshed with gear 70 which is fast on shaft 58. The hub 66 is formed at diametrically opposite points with the semi- 125 circular recesses 70^a. A locking bolt 71 is trunnioned partially in the hub 65 and partially in the hub 66 as shown in Figs. 13 and 15 and it operates in a manner similar to the well known power punch control. 130

The bolt 71 is cut away as at 72 where it extends into the hub 65 that is fast on shaft 53. The locking bolt 71 is adapted to be rotated in its seat in the hub 66 and into the recess 70^a bored in the hub 65 as shown in Fig. 13. The gear 73 is fast on the locking bolt 71 and serves to oscillate the locking bolt, this gear meshing with the gear 74 which is pivoted on the stud 75, 10 mounted in one of two diametrically opposed lugs 76 formed upon the crank hub 66. An abutting arm 77 terminating in a pawl 78 is pivoted on stud 75, and another similar abutting arm is pivoted on stud 79 diametrically opposite the one on stud 75. The gear 74 has a crank arm 80 which is pivotally connected by a connecting rod 81 to the abutting arm mounted on the stud 79. The spring 82 is secured at one point to the 20 crank hub 66 and also to the connecting rod 71 as shown in Fig. 13. The spring normally holds the two abutting arms in the positions indicated in the form of the broken line pawls 78' in Fig. 13, this position of 25 one of the abutting arms being shown in Fig. 15, whereupon it will be noticed that the locking bolt 71 has been rotated in its seat and into the recess bored in the hub 65 as shown in Fig. 15, and in that position it causes crank arm 67 to rotate in unison with the shaft 58. A revolving crank stud 83 connects this crank arm 67 with a stroking arm 84 carrying a rack 85 at its lower end (Figs. 3 and 36) this rack meshing with a sector 30 gear 86 which in turn meshes with the pinion 87 secured to shaft 87' which also carries cord pulley 88 fast thereon which moves the cord 89 fore and aft so that the ends of the cords, being attached to the 35 color-car in the usual manner will impart motion to the color car whereby it will be stroked back and forth. It will be noticed that the rocking arm 90 fulcrums on the axis 91 of the sector gear 86 so as to carry the 40 rack into engagement with the sector gear (Figs. 2, 3, and 36).

The jacquard sets up or registers the pins in the index wheel according to the design and the pawl moves the ratchet of the index 50 wheel accordingly as its lever impacts in its rearward motion against the various protruding pins, the particular pin projected at any particular time determining the distance over which the yarn carrying cylinder 55 moves at any period of rotation. The particular design may not call for making consecutive color stripes upon the yarn and it may be necessary to apply color stripes at various spaced apart intervals upon the yarn, hence the drum will sometimes move over greater distances than at other times. The index wheel provided has fewer pins than there are teeth around the circumference of the yarn cylinder, so it may be necessary to 60 turn the index wheel one or more times to register the intervals apart between which color stripes are to be applied to the yarn on the drum. In other words the cylinder may have to make several moves before it comes to rest to receive a color stripe. In 70 this event it will be necessary to prevent the premature operation of the color applying mechanism furnished by the color car. The range of movement of the pawl 41 covers twenty-four ratchet teeth or practically one-half of the total number of teeth on this index wheel; therefore any pin 30 projected opposite any of these 24 teeth assures that pawl 41 will turn the index wheel and consequently the drum a similar number of 80 teeth. As this takes place the color car is running back and forth on its track applying a color stripe to the yarn whenever the drum has ceased to rotate. So far the mechanism described is adapted to enable the cylinder to move over distances representing intervals up to 24 teeth or one half a revolution of the ratchet-wheel. It may, however, be necessary to move the drum or cylinder over a greater distance. This being beyond 90 the power of the pawl lever 40 to accomplish by a single stroke it will be necessary for it to make a double or duplicate stroke, the drum during this event, making two corresponding moves and therefore stopping 95 twice, as it stops during each back stroke of the pawl lever 40. However as the color-car strokes the yarn of the drum every time the drum stops it will be necessary to cut out the latter's operation during the first 100 stop of the drum and immediately reactuate it when the drum makes its second stop after having moved over the required distance, because the requirements of the carpet design has called for this larger skip of the 105 ratchet wheel.

The mechanism required to stop the movement of the color car must operate in such a manner that the color-car will be stopped for as long a time as required in a position 110 representing either extreme of its movement where it will be out of contact with the drum. It is necessary to cause some impediment or check to operate to arrest the movement of crank arm 67 through the abutting arm 78 after the color motion has made a scheduled number of impressions. To effect this result I provide a primary and a subsidiary color control device consisting of a bell crank lever 92 (Figs. 2, 3, and 27) 115 fulcrumed on stud 93 and having one arm 92' held slightly above the dead stop 46 by means of the spring 94, while its other arm 95 is pivotally connected to the connecting rod 96, the other end of which is connected 120 to the lever 97 fulcrumed at 98 and provided with a cam end or portion 99 shown in Figs. 27 and 29, this cam end adapted to bear against a cam 100 on the arm 101 of the lever 102 fulcrumed intermediate its ends upon 125 130

the pin 103, the arm 104 of lever 102 carrying a segmental member 105 adapted to be contacted by the curved end 106 of a lever 107 pivoted on the pawl lever 40 at 108 (Figs. 27, 28 and 29). The lever 107 is a bell-crank lever and the arm 109 thereof carries the roller 110 adapted to project into a notch or recess 111 on the rim 112 of the index wheel 27 in line with the spring pin 64, this notch being cut directly into the circular rim or ring 112 fast on the index wheel, the spring 113 being adapted to retract the roller 110 into the notch 111 when the pawl lever 40 is arrested during its rearward stroke by the spring pin. I have provided a forty-eight jacquard impelled pin 114 retracted by cam 114' isolated from the pins 30 and have placed it directly in the center of recess 111 so when the pin 114 is in its projected position, it will block up the recess 111 and prevent the entrance of the springs impelled roller 110 thereinto. The arm 101 of segmental lever 102 carries at its end 115 a connector 116 shown in Figs. 1, 29 and 37 which is attached loosely to the tail 117 of the hook member 117 fulcrumed upon the pin 118 carried by the lever 119 (Figs. 16 and 37) fast on one end of shaft 121. The lever 120 fast on the other end of the shaft which is free to rotate in a suitable bearing carries the roller 122 at its upper end, the roller being acted upon by either lobe or nose of cam 123 fast upon the continuously rotating shaft 58 as shown in Figs. 16 and 37, a spring 124 acting to normally position the lever 120 when not acted upon by the move of the cam 123. The hook member 117 carries the oppositely extending hooks 125 and 126 at its upper end adapted to engage either with the dead stop lever 127 or with the trigger lever 128. The lever 127 has a slot 127' in which projects the pin 127" serving as a fulcrum for lever 127. The end 130 of lever 127 is cam or wedge-shaped and is adapted to be engaged by the stop shoulder 131 formed upon the trigger 132, the stop 131 being normally held in engagement with the cam edge 130 of lever 127 so as to prevent this end of lever 127 rising higher thus holding end 127' in operative position, the stop 131 being urged against cam 130 by the spring 133 secured fixedly at 134. The trigger 132 is suitably fulcrumed at stud 135. The lever 128 is fulcrumed at 129 to lever 127 and has a cam head 136 inclined similarly to the inclined edge 137 of stop 131. The lever 128 is normally held by spring 138 in the position clearly shown in Fig. 16 where the cam edge 130 of the lever 127 is held out of engagement with the trigger 132. The primary color-control directs the stoppage of the color car whenever the index lever 65 makes a full reverse sweep and contacts the

rear dead stop lever 92, whereas the subsidiary color-control regulates the stoppage of the car whenever the index lever checks against the spring pin carrying lever 107 to actuate lever 102.

70

It will be seen that a friction clamp 139 is provided for the purpose of applying frictional resistance to the movement of the crank arm 67, this clamp being provided with opposing arms 140 and 141 bearing 75 against hub 66 of crank arm 67, in the well known manner of ordinary punch presses.

The color car 142 is provided with V-grooved track wheels 143 which rest upon and are guided by the track 144 as is the usual practice. The color car is adapted to loosely receive a color box 145 which retains the dye that is transferred to the yarn on the cylinder 1, by the color roller 146 which is journaled in the car and the lower portion 85 of which is immersed in the dye (Figs. 4 and 39). The top part 147 of the color car 142 upon which the color roller 146 is journaled is hinged at 148 to the main portion of the color car and is kept up by the action 90 of spring 149 all as in customary practice in printing drums. The top part of the color roller is normally positioned a little above the bottom most position of the yarn cylinder and is designed to contact with and 95 be pressed down as it engages the cylinder against the yielding resistance of the spring 149. The crank 67 as above described, strokes the color car back and forward under the yarn cylinder and at each stroke a stripe 100 of color is laid against the yarn thereon by the color roll. The pusher 50 moves to make the index pawl turn the index wheel and consequently also the yarn cylinder during the time the color car is out from under the 105 yarn cylinder, and for any jacquard indicated skip of teeth up to twenty-four teeth the cylinder turns accordingly while the color car is out from under it, passing to one extreme position and coming back again to 110 contact the cylinder again in its new position. A skilled hand operating printer can make skips of from fifteen to twenty teeth without stopping the action of the color car and he tries to bring the cylinder to rest before the returning color car can contact the yarn because if the cylinder be moving when the roller hits the yarn the result is a crooked line instead of a straight streak of color.

My automatic device will make accurate 115 maximum skips of twenty-four teeth, without stopping the color motion. In the regular hand operated printing drum the colors in the car are changed by the hand; also whenever the dye becomes too low in the box 120 so that insufficient color for a correct stripe is picked up by the roller; then more dye is manually poured into the color-box from a pitcher.

In some cases the printer stops his hand 125

indexing of the yarn cylinder and adds color from the pitchers to the partially exhausted box, also when necessary he changes from one color box and roller to another and new 5 color; while in other instances an assistant attends to these details. I will now describe my device for eliminating the personal element and for automatically accomplishing these two functions.

10 I provide a magazine with four shelves that are equipped with a set of planetary gearing that allows them to revolve around their common center and always remain horizontal. The shelves can be made as long 15 as desired and are supplied with forms and clip springs to hold the various color boxes, and their pitchers with the additional color, if such are required. The operative "sets up" his magazine with the necessary boxes 20 and pitchers as per the instructions that go with the perforated jacquard strip, moves the magazine over into its first station, hitches on the traction rope and starts the machine. He then proceeds to attend to 25 other similar automatic machines while my novel mechanism changes the various colors, adds dye to depleted boxes from the waiting pitchers and does all of the printing from start to finish without assistance or supervision.

30 The index end of a printing drum is the end where the internal gear 12 is located on the yarn cylinder. Fig. 2 shows the hand wheel fast on shaft 15 with the hand turning gear 14 fast on the other end of the shaft and in mesh with the internal gear 12. In the hand controlled machine the operative 35 positions the yarn cylinder by the hand wheel, shaft and gearing and I attach my spiral gear 39 to the same shaft and position it by the same shaft and gear.

40 The magazine end of the printing drum, or cylinder, is opposite to the index end.

45 The magazine (Figs. 6 and 7) the initial source of color supply is composed of two frames 150 and 151 held apart by suitable girts 152 and 153. There is a central shaft 154 journaled in the frames 150 and 151 and at each end thereof and located inside each 50 frame is made fast a four-armed spider 155 in which are journaled the four shafts 156 that hold fast thereon the shelf bracket 157 to which are attached the shelves 158. A central gear 159 is made fast to the frame 55 151 and its center coincides with the center of the central shaft 154. Four intermediate gears 160 mesh with this central gear and are pivoted on studs 161 on each of the four arms of one of the spiders. Four gears 162 60 are made fast respectively to one end of each of the shelf shafts 156 and mesh with the intermediate gears, thus constituting the well known device for keeping the four shelves which are fast on the shafts always 65 level with the pitcher holding forms on top.

The forms 162 and 163 and spring clips 164 (Fig. 5) are designed to act as a common means for holding either a color-box 145 or a dye pitcher 165 which may be placed and safely retained at any station on any of 70 the four shelves there being more than enough stations or forms 162 and 163 for the colors used in the pattern being printed. The magazine is supplied with rollers 166 that fit into and are guided by the tracks 75 167 which extend transversely of the regular color-car track 144. The pull cord 168 is attached to one end of the structure at 169 and from thence passes around the pulley wheels 170 and 171 and the traction 80 weight 172 is made fast to the other end and gives sufficient pull to move the magazine for its full length freely along the track. At the opposite end of the magazine to the gears 161 I attach the gear 173 to the 85 central shaft 154 and mesh intermediate gear 174 with it where it is free to turn on the stud 175. The combined gear 176 and ratchet 177 are fast together and revolve freely on stud 178 held in the frame 150 and 90 the gear 176 meshes with the intermediate gear 174. The pawl lever 180 is pivoted on the stud 178 and carries the pawl 179 pivoted on the stud 181, that is adapted to operate with the teeth of the ratchet 177. 95 The downwardly extending arm 182 of the pawl lever is matched by a similarly disposed arm 182' pivoted on the stud 183 located in the opposite frame 151, and the bar 184 extends from arm 182 to arm 182' 100 and is made fast to each so that a to and fro movement of the bar 184 will oscillate the pawl lever and pawl and cause them to periodically operate the ratchet 177 which will rotate the central shaft with the spiders 105 carrying the shelves and their load of color boxes and pitchers. Four operative strokes of the pawl will rotate the magazine one full turn. The pawl lever 180 receives its motion through the connector 185 which extends from a lever situated near the index end of the yarn cylinder, the operation of which will be described later.

110 The connector 185 is hooked at 185' (Figs. 6 and 7^a) over the bar 184 and when the magazine moves longitudinally along its track the bar 184 slides through the hook 185' of the connector and when the magazine comes to rest at its new station the connector 185 is positioned at a new station 120 on the bar 184 and is all ready to actuate the pawl again.

125 The magazine is prevented from moving freely along the track by the fact that the roller 502 pivoted at 503 on floor stand 504 (Figs. 6 and 8) is standing in the way so that any stop plate 505 fast on shaft 506 abuts against the roller thus stopping the magazine at that station; the four positions on the four shelves for each station are 130

known as sub-stations. The stations follow one another in a step by step order and the color boxes are set on the shelves of the magazine in the order in which the operative 5 has been instructed, which is the same order that was used when the jacquard perforated strip was made. There are four sub-stations (one on each shelf) to every longitudinal stop station and there must be 10 a continuous set of boxes up to the final box, one on each sub-station, although there need not be a continuous set of pitchers because a pitcher is supplied for a box simply as a 15 source of supply therefor for additional dye of the same color. It should be clearly understood that the stations are all box stations although there may be pitchers at stations; no stop plate is supplied for a pitcher station, for a pitcher is simply incidental to 20 a box.

Shaft 506 is journaled in the two frames 150 and 151 and rotates in unison with the shaft 154 of the magazine, receiving the motion therefrom through the meshed gears 25 507 fast on shaft 154, the intermediate 508 pivoted at 509, and 510 fast on shaft 506. The stop plates are located fast on the shaft 506 so as to register with the magazine stations holding color boxes as shown in Fig. 30 7, and there is no stop plate for a pitcher substation. Each stop plate is provided with an opening 511 that is larger than the roller 502 and the opening is positioned so that the roller will rotate along the face and 35 stop rolling at four places on the plate by the action of the ratchet, *i. e.* 512, 513, 514, and 515 to agree with the four annular positions of the shelves of the magazine; thus as the stop plates turn with the shaft 40 506 the opening 511 will come opposite the roller between positions 515 and 512 and the pull of traction weight 172 will cause the magazine to move longitudinally because the stop plate escapes from the roll when the 45 opening comes opposite to it, Figs. 6 and 8. Thus the longitudinal movements of the magazine are automatic and are accomplished by the pull of the traction weight.

I will now describe the mechanism that 50 the jacquard controls for starting up the automatic means which not only moves the magazine circumferentially but also operates the color-box and pitcher transfer driver for doing all the color changing and replenishing 55 that on the ordinary printing drum is done manually. The jacquard has a forty-ninth vertical needle located in line with its other needles and the jacquard hook 192 that is controlled thereby (Figs. 1, 2 and 36) 60 pushes a slide 193 which is guided at 194 toward the left (Fig. 37) so that lug 193' is placed in the path of motion of the index-pawl lever 40, which is always at the zero point when the jacquard indicates, and 65 checks its rearward motion so that the lever

cannot be retracted far enough to allow the index pawl 41 to catch the first rearward tooth because the projection 42' of the pawl lever under the urge of the weight 49 impacts the lug 193' on slide 193 and is kept from further retraction thereby, and therefore the index wheel will not move again until lug 193' is moved out of the path of pawl lever 40 so it can be retracted and pawl 41 can catch into a ratchet tooth. 75

While the slide 193 is in operative position holding the index pawl lever at the zero position and through proper connections the yarn cylinder stationary, the primary color control is inactive or dead and will remain so until the slide 193 is moved back to normal, because the index pawl lever cannot move back and engage member 92'. The yarn cylinder is kept from moving so as to give time for the operation of the color transfer motion which will now be described. The operative action of the jacquard hook 192 also actuates the pusher rod 192' which extends toward the left (Fig. 37) from slide 193 and is designed to impact at 195 on lever 196 which is pivoted at 197 on sliding tooth gear 198 which, therefore, is a predetermined timing element for effecting the color change mechanism. The push of jacquard hook 192 pushes lever 196 toward the left 95 (Fig. 38) against the yielding resistance of spring 199 and causes sliding tooth 200, which forms the free end of lever 196, to swing to operative position and form a broad double tooth in the vacant portion of 100 the tooth section of sliding tooth gear 198 which is mounted fast on shaft 198' (Fig. 36) turning in bearings not shown. Upon the same shaft 198' is fastened the miter gear 202 (Fig. 1) in mesh with and driving miter gear 203 fast on the top of upright shaft 204 which is free to turn in bearings not shown (Figs. 1 and 36). Gear 201 is fast on constantly revolving shaft 58 (Figs. 1 and 36) and revolves with it and acts as 105 a timing element for the color shifter mechanism. Gear 201 has a portion of several adjacent teeth cut away laterally at 205 (Fig. 38) and as several adjacent teeth of gear 198 are entirely removed at 206 the teeth of 110 the constantly rotating gear 201 cannot mesh with and move the teeth of sliding tooth gear 198 because normally the spring holds sliding tooth 200 out of operative position. The operative movement of connector 192' 115 pushes sliding tooth 200 into place in the periphery of gear 198 at 206 where the teeth are entirely cut away and the movements are so timed that this tooth 200 swings into place just as the cut away portion 205 of 120 the teeth of gear 201 are passing the meshing point of gear 198 and thus the sliding tooth 200 is enabled to pass across the face and forms a portion of the teeth of gear 198 before the meshing tooth of gear 201 contacts 125 130

it and the continued rotation of gear timing element 201 causes tooth 207 to impact sliding tooth 200 of gear 198 and rotate in unison with 201 whereby motion is imparted to upright shaft 204 through the meshed miter gears 202 and 203. Sliding tooth gear 198 is twice as large as constantly rotating gear 201 so timing gear 201 turns twice before sliding tooth 200 gets around to the point where it can mesh again with tooth 207 of gear 201. During the revolution of gear 198 the sliding tooth 200 moves away from the end of pusher 192' and is retracted out of operative place by the expansion of spring 199, consequently sliding tooth gear 198 and the gearing and shafting rotated thereby are brought to rest when tooth 208 of constantly rotating gear 201 runs out of mesh with tooth 209 of gear 198 because tooth 207 cannot mesh with sliding tooth 200 as it is now in normal position and no longer in operative place in the periphery of its gear 198. Before gear 198 makes its full revolutions the slide 193 and pusher 192' are retracted as will be described later. The two gears 198 and 201 act as a selective coupling for the constantly rotating shaft 58 and the color change mechanism.

A portion only of the teeth 205 of gear 201 are cut away so that when the teeth 205 come around to mesh with the teeth 210 on the opposite side of gear 198 from the sliding tooth 200 the gear 198 is kept rotating by the portion of the teeth 205 that are not cut away.

At the lower end of the upright shaft 204 is keyed miter gear 211 which meshes and drives miter gear 212 keyed fast on the horizontal cam shaft 213 which turns freely in bearings not shown. When necessary a conventional friction brake can be applied to shaft 204 to keep it steady when at rest. This cam shaft carries the various cams for the automatic color changing operation, and being a unitary means for actuating and timing all the devices for making a change of color and causing a pitcher control and receiving its power periodically from continuously rotating shaft 58 and cam 215 fast thereon causes lever 216 (Fig. 36) pivoted at 217 to make its working stroke and pull the connector 185 attached freely at 219 and thus rotates the magazine by the actuation of pawl 179 against the teeth of ratchet 177 as previously described. The action of spring 218 attached to lever 216 returns the roller 221 of lever 216 to its normal and lowest position on cam 215.

The cam 222 also fast on horizontal cam shaft 213 actuates the lever 223 for moving the color boxes, it being fulcrumed at 217 and on its upper arm is pivoted the cam roll 224 which rests against and follows the contour of the cam 222. To the downwardly extending arm 225 is attached at 226 the

connector 227 which extends nearly horizontally under the yarn cylinder and ends in the rack 228 (Fig. 22) meshed with the gear 229 fast on the hub 230 of color-box lever 231 adapted for making color deliveries being the color transfer means and which is made fast to the shaft 232 that is journaled at an angle to connector 227 in bearings 233' in the member 233 (Figs. 5 and 22) which is hinged at 234 in the brackets 235 and is held in operative position by the downwardly extending leg 236 pivoted at 237 and the foot 238 of which normally fits into the socket 239 secured to the floor (Fig. 4).

The tongs transfer the color boxes *seriatim* from the magazine to the color car and vice-versa.

The tongs 240 and 241 are pivoted at 242 to the link 243 which is hinged at 244 to the free end of box motion lever 231 (Figs. 21 and 22).

The longitudinal stop stations for the magazine are arranged so that a pitcher will stand practically on a line passing through the center of the color car track 144, the reason being that the pitcher has to follow the moving car back and forth for some eighteen inches and at the same time it rises on a curve so the spout of the pitcher is closer to the top of the color box at position C than at position D although the dye is pouring from the spout at both positions. It is evident that during the operation of pouring, the pitcher should be as nearly in line with the center of the box as practicable. The above requirements having been met the color-box is placed conveniently on the shelf of the magazine at one side of the pitcher, therefore the fulcrum shaft 232 is placed at such an angle that when the box shifting lever is at position F (Fig. 4) the tongs are located to grasp the box in the car and when the shifter lever is over at the magazine the tongs register similarly with a box on the magazine that stands to one side of the center line of the color car track. The tongs proper hang parallel with the color car track at all times, the twist in the link 243 bringing the center line of the tongs joint pin 242 at right angles with the track, the terminals of the tongs being hooks.

The tongs transfer the color boxes *seriatim* from the magazine to the color car, and at proper times back to the magazine again. They are opened by means of the double curved cam pivoted lever 245 which being pivoted on the shaft 246, is equipped with the two cam points 247 and 248 to enter in turn into the inverted V-shaped recess 249 formed by the two confronting abutting surfaces 250 and 251 each respectively forming a part of the tongs 240 and 241 and force the tongs apart. The cam or wedge shaped point 248 actuates the tongs while they are operating at the magazine (Fig. 21). Le-

ver 245 is fast on the shaft 246 which is journaled in the bearing 253 forming a portion of box moving lever 231. The other end of shaft 246 carries the lever 254 fast thereon, it being so positioned that the lug 255 thereon coincides substantially with the center of the fulcrum shaft 232. Lever 256 is pivoted on the stud 257 fast in member 233 and is adapted to act upon the lug 255 5 of lever 254 and thereby open the tongs at the necessary and proper moments (Figs. 20 and 22). Lever 256 receives its operative motion through the connector 252 attached loosely at the stud 257 fast in the lever, 10 while the other end of the connector 252 is pivoted at 258 on the cam lever 259 which is pivoted at 217 and which carries the roller 261 which rests on and follows the contour of the tongs opening cam 262 fast 15 on cam shaft 213. The action of spring 263 attached to cam lever 259, retains the roller against the cam and holds the double cam pivoted lever out of operative position 20 with the tongs.

25 The color box cannot be removed from the color car until the box registers accurately with the movements of the transfer tongs 240 and 241 and therefore I have prepared a color-car positioner which receives 30 the incoming car as it moves along the track 144 and nears the magazine end thereof, to force it and its box into accurate register with the tongs.

35 The car is drawn along the track by the cord 89 and therefore it does not reach its extreme position with the necessary degree of exactitude because of the elasticity of the cord. I have arranged two vertical shafts 265 (Fig. 39) and 266 in bearings 265' and 40 266' and upon 265, which stands directly in line with the incoming car, I have fastened an abutting arm 267 which can be placed through an angular movement of shaft 265 in line with the car. The shaft 266 is connected to 265 by means of the connector 268 which is pivoted to the arms 269 and 270 at 271 and 272, the two arms being respectively fast on shafts 265 and 266. Shaft 266 is set somewhat at one side 50 of the color car and the arm 273 is fast thereon and is adapted to be swung in behind the car when the shaft 266 turns and upon contacting the car its continued motion will move the car toward the magazine and if necessary stretch the cord somewhat, until the car contacts against the abutting lever 267 and thus it is held in position so as to register with the descending tongs. Shaft 266 also carries the arm 274 fast thereon 55 and to this arm 275 is freely attached the connector 276 which extends back under the yarn cylinder and is attached at 277 to the cam lever 278 which is fulcrumed at 217 and which carries a roller which bears 60 65 against and follows the contour of the cam 281 fast on horizontal cam shaft 213. A conventional spring is attached to the cam lever 278 and its pull keeps the roller 280 on the face of the cam so that the contour thereof actuates the cam lever 278 and consequently the placer levers 267 and 273.

70 The color roller 146 is removed with the color box and consequently must be uncoupled from its driving mechanism. The sheave 284 is revolved in the conventional 75 manner as is customary and I have provided a lever 285 pivoted at 286 which contacts the flange 287 forming a part of the square shaft coupling 288 which loosely attaches the square end 289 of the axle 290 of the sheave 284 to the squared end 291 of the axle 292 of the color roller. The operative movement of shaft 266 of the car positioning mechanism is designed to uncouple the color roller 146. The lug 293 fast on lever 273 contacts against lever arm 285' at 294 and moves it so that the lever 285 is moved against the tension of spring 295 and as it straddles the flange 287 of the coupling 288 the coupling is moved away from the square end 291 of the color roller axle 292 thus releasing the roller from its driving mechanism 80 so that when the color box is raised out of the car the roller which is in the box will be raised out of its bearings and both be deposited on the shelf of the magazine. Each station of the magazine is equipped with the fork 296 (Fig. 4) the function of which is to receive the journal end 297 of the axle 290 and hold it in proper alinement while 85 the roller is in the box in place on the shelf of the magazine. When the box is grasped and lifted by the tongs the roller is lifted out of the fork 296 and as it is resting on the bottom of the color box, and also because the hubs of the axle project out through the openings in the side of the box and fit somewhat snugly therein, there is no tendency to displace the relative position of the box and roll, and therefore the journals of the axle enter properly into the bearings prepared for them in the color car. The retraction of the lever 273 allows the spring 295 to expand and force the coupling 288 over the square end 289 of the roller 90 95 100 105 110 115 120 125 130

135

The mechanical scrapers 298 and 299 are a part of the regular equipment of the color car of a printing drum and my selectively automatic control of such scrapers is clearly

disclosed and claimed in my pending application filed Aug. 20, 1919, series 1915, No. 318,716. It is necessary to wipe the scrapers before beginning to print a different color, 5 and on the hand controlled machine this is done by either the printer or his assistant, but as mine is an automatic machine, and as the colors are changed without the assistance of the operative, I have provided two 10 wiper-arms 300 and 301 attached respectively to the two vertical shafts 265 and 266 and have provided them with the wipers 302 and 303 which are composed of absorbent cloth or other suitable material. They are so situated 15 that the wipers come in contact with the two scrapers 289 and 299 and are passed across the scraping surfaces so as to remove the small amount of color that adheres to the surface. The so called scrapers are 20 really rubbers and their object is to smooth down the color ridges formed between color impressions and distribute and rub the surplus color into the adjacent yarn.

The various color-boxes on the magazine 25 are supplied with color when the load or change of the magazine is being made up, there being enough dye for thirty stripes of color on the average in a box before the level of the liquid is lowered to a point where 30 the color-roller may fail to pick up sufficient color to make a satisfactory color impression on the yarn on the cylinder. With the hand controlled drum the printer, or his assistant, refills the color-box that is being exhausted 35 and as the car makes about thirty strokes in a minute it is necessary to refill a box approximately once every minute. In order to do this same thing in an automatic manner I have provided holders or forms 162 on my 40 magazine for the reception of standard dye holding pitchers 165 containing one gallon of color and pitchers containing this extra dye, which will make the two hundred and forty stripes that are placed on the magazine according to the requirements of the 45 pattern being printed. Some colors in the design will not require pitchers, because a box will hold a sufficient quantity, while those colors that appear most frequently may 50 require two or more pitchers to give a full quantity of dye. When the design calls for more than two hundred and seventy strokes of the same color, thus using all the color in one pitcher as well as the color for the thirty 55 strokes originally in the box, then it becomes necessary to start the color box and pitcher shifter motions so that the exhausted box and pitcher can be put back on their original places on the magazine, and the second box 60 and pitcher of the same color already waiting on the magazine at the succeeding station can be placed in action. Sometimes it is necessary to repeat this several times for it depends on the coloring of the design as 65 to how many strokes of one color are made

on one hank of yarn on the cylinder. The action of the automatic box and pitcher shifter is the same whether a wholly new color is to be brought into working position or simply another box and pitcher of the 70 same color. However the manner of starting up the shifter motions is entirely different in the two cases. New colors are always called into action by the jacquard. Additional color in the shape of a fresh box and pitcher, 75 to continue the application of the same color, is always moved into operative position by the action of a feeler or detector that gages the amount of color in the moving color car and at the proper moment set in motion suitable means that causes a definite quota of 80 dye to be spilled from the waiting pitcher into the color box in the moving car without stopping the stroking of the car. After the eighth quota has been poured into the box 85 the car proceeds to make thirty more strokes thus using up the last or ninth quota of that color (one originally in the box and eight from the pitcher) the feeler will call into action a ninth tilt of the pitcher which is 90 already empty and the actuation of such a ninth tilt will start the color shifter into activity entirely without the intermediary of the jacquard. I will now proceed to describe the feeler and the allied devices that 95 cause the dye to be spilled from the pitcher in definite quotas into the car, and the manner in which the ninth tilt of the pitcher procures fresh box and pitcher of the same color. 100

It is customary to use a wooden float 305 (Figs. 1, 39 and 40) on top of the dye in the color box because its presence tends to prevent the stopping of the color during the somewhat rapid reversal of direction of the 105 car during printing. I attach a light wire 306 to the float and shape it to project out through the opening 307 in the side of the color box. Such openings are common to all color boxes and are primarily intended for 110 the hubs of the color rollers. I arrange my wires so that they project beyond the side of a box, and float about an inch above the hub of the color roller when the box contains the requisite volume of dye. 115

Thirty strokes will, on the average, lower the surface of the dye in the box about nine sixteenths of an inch, the number of color stripes obtained from such a quantity of color (about fifteen liquid ounces) being dependent on the width of the color-roller, the character of the doctors operating on the roller, the width of the yarn as the cylinder surface being printed, etc., and I place my float-supported wire in the center of the 120 length of the box because there it is less disturbed by the waves induced in the liquid by the rapid motion and quick reversal of the car. This gives me a point for outside contact that is supported by the liquid in 125 130

the box which registers the level of the dye and is comparatively motionless vertically as it slowly sinks with the lowering of the surface of the dye in the box as the color 5 is used up in the printing. I have arranged feeler lever 308 at the opposite end of the cylinder from the magazine to act as a timing element actuated by the color car and have hinged it at 309; the feeler 310 is 10 heavier than the tail 311 so that the lever tends to tip downward at the feeler end (Fig. 26). The feeler is a tilt indicator as well as register and predetermines the successive pourings from the pitcher. Weight 15 lever 312 is pivoted at 313 and the weighted end 314 rests on the tail end 311 of the feeler lever 315 and presses it downward against the stop 316. Arm 317 of lever 312 has a cam shaped surface 318 adapted to be contacted 20 by and moved upward by the pin 319 (Figs. 1, 5, and 40) attached to the color car 142. As the car moves toward the feeler the float supported wire passes under the up lifted feeler 310 and when the pin 319 contacts 25 with the cam 318 the continued motion of the car is sufficient, before it reaches its extreme position, to raise the weighted end 314 of the lever 312 and thus allow the overbalanced feeler to drop upon the float-supported wire that is adapted to receive it, for 30 the feeler extends longitudinally with the traverse of the car and is long enough to contact with the float sustained wire 306 even if the car does not always come to rest 35 in exactly the same place. The feeler 310 thus "feels" of the float supported wire 306 and is stopped upon contact therewith at a level corresponding to the level of the liquid in the color box. I provide an escapement 40 wire 320 attached at 321 to the pawl 322 that is pivoted on stud 323 fast on arm 324 of slide 325 which is pivoted at 326 on lever 327; the other end 328 of the slide is supported in bearing surfaces not shown (Fig. 45 26).

Escapement wire 320 leans at its top against the tail 311 of the feeler lever 308 the weight 314 of the pawl 322 pressing it in that direction and as the surface of the liquid 50 in the color box sinks lower and lower the feeler 310 drops more at each incoming stroke of the car and consequently the tail 311 rises that much higher at each indication until finally the end 320 of the escapement wire passes under the tail 311 and swings around stud 323 until the end of pawl 322 contacts with the upper surface 329 of slide 330. This is a constantly stroking slide acting as a movement controller 55 and it receives its motion from the continuously rotating cam 331 fast on constantly rotating crank shaft 58 because the roller 332 which is pivoted on lever 333 rests on and follows the contour of the cam 331 and 60 thus, through the connector 333' attached at 334 to the lever 333 transfers its working stroke to the slide 330 through the lever 335 hung on stud 336 and attached to the lower end of the connector 333' at 337 while the slide 330 is hinged at 338 to the arm 339. 70 Slide 330 is provided with a tooth 340 adapted to contact with the working end of pawl 322 whenever the liquid in the color box is exhausted to an extent that allows the feeler to sink low enough to enable the escapement wire 320 to pass under the tail 311 and allow the pawl 322 to drop into operative position with the tooth 340. The cam 331 gives the slide two distinct forward impulses and then the contraction of spring 80 341 attached to lever 335 retracts the slide to its normal position. The spring 342 attached to lever 327 retains the tooth 343 of slide 325 against the stop pin 344 and when the tooth 340 of constantly reciprocating 85 slide 330 hits against the end of pawl 322 the continued motion of slide 330 is transmitted to slide 325 and consequently the lever 327 to which it is hinged so that lever 327 turns on its pivot against the strain of 90 spring 342 and the arm 345 of the lever is depressed carrying with it the connector 346 which extends from lever arm 345 to lever 347 and is attached respectively to each at 348 and 349. The connector 346 is equipped 95 with a slot at its lower end 348. Thus lever 347 is moved on its pivot 350 and the arm 351 contacting against the end 352 of sliding cam 353 pushes it along shaft 58 on the feather key 354 against the pressure of spring 355 which encircles the shaft and abuts against the collar 356 fast on shaft 58. Hence the level of the dye in the color box predetermines the longitudinal movement of the sliding cam 353 on the shaft 58. 100 After one of the rollers 412 or 416 has dropped down into the opening caused by the contour of either cam 411 or 415, all of each two cam surfaces being below the outer dwell surface 353' upon which the two rollers are shown as riding in Fig. 26, 26^A and 26^B the lever 347 which pushed the cam over into operative position can be retracted but the cam will remain in place because the side of the roller will bear against the side or 115 web of the cam, all the working part of the two cams being below the common dwell for that very purpose, and thus hold it in place against the pressure of the spring 355 and the cam cannot slide back into its normal place under the urge of the spring until the roller which has been holding it in its longitudinal place on shaft 58 has been cammed up out of the depression at the end of the cam movement and raised as high as 120 the common dwell 353' of the two cams and then the spring can expand and push the cam toward the left to normal position, and when the cam slides back to normal the color replenishing is finished. 125 130

The movements of the two slides 330 and 325 are illustrated in the diagrammatic views #23, 24, and 25. Slide 330 is constantly reciprocating for as already described, it receives two forward impulses toward the right and one return move from the cam 331 that is timed, on constantly rotating shaft 58, to work in unison with the color car stroking crank 67 driven by the same shaft. The action of feeler 310 occasioned by the arrival of the color car at the index end of the yarn cylinder, takes place when the member 319 on the car contacts with and lifts the weight lever 312. The escapement 15 of the wire 320 from under the tail 311 of the feeler that is resting on the float supported wire 306 allows the end of pawl 322 to drop into the slide 330 that is at a momentary stop at its extreme left hand position. 20 The reverse stroke of the color car will withdraw member 319 from contact with the cam shaped arm and allow the weight lever to drop upon the tail of the feeler and pins it down against rest finger 316; therefore the 25 slide 330 receives its first forward impulse, contacts tooth 340 against the end of the pawl, and pushes the pawl carrying slide 324 to the right as shown in Fig. 24 far enough and quickly enough to get the tip 320 of the 30 escapement wire back again into the right hand side of the tail 311 so that when the weight forces it down, as shown in dotted lines in Fig. 24, the wire will be out of the way of the descending tail and on the normal 35 side thereof. This first movement of slide 325 does not cause lever 345, through connector 346 and shifting lever 347, to move the sliding cam 353 because the movement is idly taken up by the slot 346' in the lower 40 end of the connector, but upon the second impulse the motion is transmitted to the lever 347 and the double cam is slid along on its farther lug just as the two rollers 412 and 416 are in line with the common dwell 45 surface 353', the cams 411 and 415 being held in line with the rollers by a dwell on cam 331 until the continued rotation of the shaft 58 allows them to drop down into the cam recesses after which the slide 330 can be 50 retracted to get in place for its next impulse while the sliding cam will be retained in position by the side contact of the rollers until they are forced out upon the periphery of the cam and the expansion of spring 355 55 can move the cam back to normal once more. The spring 342 will then contact and move slide 325 to normal and the escapement wire will be on the operative side of the feeler.

I will now describe how a pitcher is re- 60 moved from the magazine, held ready to add color to a depleted color box and then tilted so that about one pint of dye will pour into the box, the successive tilts increasing the angle at each pouring as the level of the 65 liquid lowers in the pitcher.

Cam shaft 213 is equipped with cam 357 fast thereon (Fig. 26) which acts upon lever 358 through roller 359 (hidden by the cam) pivoted to the upper end of the arm thereof and which is hung on the stud 360. From 70 the lower end 361 of lever 358 extends the connector 362 connected at 363 and the other end of the connector terminates in the rack 364 meshed with the gear 365. The rack 364 is attached to the end of connector 362 at 75 364' by a hook which allows the operative to disconnect the two whenever it may be advisable, as will be more fully explained. Normally pitcher lever 367 stands at position A (Fig. 9) and moves toward the magazine to B position and back to normal again by virtue of the rotative engagement of cam 357 with lever 358 through its connector to shifter lever 367. The box shifter is meanwhile going through nearly the same movements as already explained, for the levers move toward the magazine simultaneously. 80

The gear 365 is pivoted at 366 and pitcher lever 367 is attached to the hub of the gear so that a to and fro movement of the rack 90 364 will cause the lever to oscillate about its pivot 366. The top of pitcher lever 367 carries the pitcher grasping device illustrated on Figs. 9, 10, 11 and 12. The swivel plate 368 is pivoted on the gudgeon 369 in the top 95 lever 367 and is provided with the sector gear 370 made fast thereon which meshes with rack 371 and is positioned thereby as will be clearly described later.

Fig. 11 shows an enlarged view of a 100 pitcher 372 grasped by my device and tilted sufficiently so a portion of the dye contained therein will flow out as illustrated at 373. The swivel plate 368 has the boss 374 and the shaft 375 is journaled therein and carries the ratchet segment 376 fast thereon, while the bottom-pad lever 377 carrying the pads 378 is likewise made fast to the same shaft. The pitcher is positioned on the magazine shelf to project somewhat beyond the edge of the shelf so the pads 378 can readily contact the bottom of the pitcher. Pad lever 377 is also provided with the double pads 379 which are adapted to bear against the cheek of the pitcher on each side 105 of but lower down than the spout. These pads 379 are separated at 380 so that they do not touch the pitcher in a line directly under the spout and thus the drip of the dye after a pouring can flow down the outside of 110 the spout, between the two pads, and drop off the bottom of the pitcher without flowing onto any portion of the grasping or tilting mechanism. Pads 379 are constructed on a radius struck from the center of shaft 375 115 and therefore the turning of lever 377 will not alter the pitcher contact point in its relative distance to the center of the gudgeon 369. Ratchet 376 is acted upon by the pawl 381 pivoted at 382 on arm 383 of swivel 120 125 130

plate 368. The swivel plate is also provided with the arm 384 which has the boss 385 that is bored to form the bearing for shaft 386 that carries the lever 387 fast thereon, and from lever 387 extends the connector 388 from the point 389 to joint 390 on the ratchet segment 376, so that the two shafts 375 and 386 move in unison but in opposite directions. Shaft 386 also carries fast thereon the lever 391 with the two pads 392 fast thereon which are adapted to straddle the handle and contact the pitcher some two inches down from the top thereof. The finger 393 is formed integral with the arm 384 of the swivel plate and is formed and positioned to swing freely over the spout of the pitcher and then downward, as the lever 387 revolves about its pivot, and come to rest without hitting the inside of the pitcher although it extends about an inch below its top. The pawl 381 is made to click sharply into the teeth of the ratchet segment by the pull of spring 394 one end of which is attached at 395 while the other end is similarly attached to the spring arm 396 which is fast on shaft 385. The spring not only acts on the pawl but also retracts the shaft 386 and by means of the connector 388 it also retracts the shaft 375. Fig. 10 shows the various parts of my pitcher grasping mechanism as thus retracted and when in the position shown they will not grasp the pitcher. The actuating mechanism for causing these pads and the finger 393 to grasp the pitcher and hold it firmly enough to enable it to be tilted from the vertical sufficiently to cause all its liquid contents to flow out will be fully described farther on for the method of tilting will now be described.

As above stated rack 371 meshes with gear 370 which is swivelly attached and forms a part of the swivel plate 368 and the rack 397 is formed on the lower end of the bar 371^a just as the upper end forms the rack 371. Gear 398' meshes with rack 397 and the gear is sufficiently broad to enable it also to mesh with rack 398 forming the magazine end of the connector 399 the other end of which, after passing between the guide pins 400, is formed into a pin 401 which enters into slot 402 formed in the lower arm of the segmental lever 403 pivoted at 404, and the horizontal arm 405 moves the connector 407 attached at 406 and extending upward until attached at 408 to the lever 409 that is fulcrumed at 410 and acted upon by the cam 411 of the sliding cam 353 contacting on the pivoted roller 412. Cam 411 causes the tilting of the pitcher so that dye may be poured out of it into the color box. The downward movement of lever 409 and connector 407 caused by the contour of cam 411 from *a*—*b* as the roller 412 is made to contact the cam by the contraction of spring 404' which is attached to bell crank lever 404 makes rack 398 (Fig. 26) move toward the right and causes the tilting of the pitcher through the connecting gearing and racks, while the rising of the same lever and connector by the cam curve *b*—*f* causes the pitcher to swing in the opposite direction back to vertical. The lever 413, fulcrumed at 414, is similarly acted upon by the cam 415 of sliding cam 353 through the pivoted roller 416 and at 417 is freely attached the connector 418 which extends downward and connects at 419 to the lever 420 fulcrumed at 421. Therefore the pitcher has a plural actuator, for both levers, 358 and 420, stroke 80 the holder of the pitchers. The contour of cam 357 (Fig. 26) causes lever 358 to turn on its fulcrum 360 and oscillate lever 367 from normal position 424 or A (Figs. 9 and 26) to the magazine and then back to normal whereas the contour of cam 415 of sliding cam 353 causes fulcrum stud 360 fast in arm 423 of lever 420 to move about fulcrum 421 and make lever 367 swing from its normal position A over toward the yarn cylinder to position C (Fig. 9) and then back to normal at A. At 426 on connector 407 is freely attached the connector 427 the other end being pivoted at 428 to the pawl lever 429 that is fulcrumed on shaft 430. Cam 411 is so shaped that while the roller 412 on lever 409 is passing over its contour from *a* to *b* (Fig. 26^A) the lever gradually drops farther and farther downward as the cam curve continues to approach the shaft so the rack 398 is correspondingly slowly moved to tilt the pitcher farther from the vertical and a constant stream of liquid be poured from the spout of the pitcher.

Cam 415 is formed (Fig. 26^B) so that the roller 416 on lever 413 will follow the descending curve *c*—*d* and swing the pitcher carrying lever 367 from normal at A to C (Fig. 9) in which latter position the pitcher meets the incoming color car with its exhausted color box, at which point the pitcher has been tilted sufficiently to begin to pour a stream of dye into the box. The continued rotation of cam 415 forces the roller up the incline *d*—*e* against the tension of spring 361' until the pitcher reaches position D where it stops as the car stops, then follows the out-going car as the roller moves down curve *e*—*d'* till the pitcher reaches position C again and the pitcher is tilted toward the vertical so the pouring stops. The roller is then forced up the incline of the cam *d'*—*c'* which brings the lever 367 and its pitcher back to normal at A. Roller 412 reaches *f* of cam 411 at the same time that roller 416 reaches *c'* on cam 415 and as both these surfaces coincide with the common dwell surface 353' of the double cam 353 the spring 355 can expand to force the cam toward the left so the two rollers will ride upon the

circular dwell surfaces as shown in Fig. 26 until the cam is moved over once more by the action of the feeler motion indicating the next exhaustion of the color box after 5 about twenty strokes.

During the course of any single tilt the angularity of tilt will vary sufficiently to allow all the dye to be poured out of the pitcher that is required for the full quota 10 for that tilt, the contour of cam 415 allowing this variation of angularity.

Levers 358 and 420 (Fig. 26) act in unison and form what is known as a compound lever, the various positions of which are 15 illustrated in the diagrammatic views, Figs. 33, 34 and 35. Cam 357 (Fig. 26) moves lever 358 which causes pitcher shift lever 367 to move from normal position A over to the magazine to position B at right hand 20 of Fig. 9, back to normal again and while thus moving about its fulcrum 360 the lever is one of the first order with the load at one end *i. e.* 365, the force at the other end or 25 359 while the fulcrum is intermediate the ends 360. The contraction of spring 361' keeps the roller 359 against the cam surface. The fulcrum 360 of lever 358 is fixed in the arm 423 of the bell crank lever 420 that is fulcrumed at 421 fast in a bracket, not 30 shown, that is attached in a conventional manner to a suitable part of the main frame of the printing drum. The contraction of spring 361' likewise causes roller 416 of lever 413, through the connector 418 to bear 35 quite strongly against the periphery 353' of the double sliding cam of which cam 415 is a part. As soon as the sliding cam is slid over to operative position the cam 415 comes in line with the roller 416 and the pull 40 of spring 361 urges the roller and lever down the incline *c-d* of cam 415 (Fig. 26) thus allowing the connector 362 and rack 364 to move toward the right and swing 45 pitcher lever 367 toward the yarn cylinder to meet the incoming car. During this action the lever 358 is fulcrumed at the center of the roller 359 which is resting on the idle cam 357 while the spring 361' is the active force. The upward urge of connector 418 50 caused by the roller 416 being forced up the incline of cam 415 causes the spring to become the load while the moving force is applied by the cam 415 at 360 by the bell crank lever 420, that is free to revolve in 55 bearings not shown. The pawl lever carries the pawl 431 pivoted at 432 and it works with and operates on the teeth of the ratchet 433 that is fast on shaft 430 while the ratchet is retained against rotation by hold pawl 431'. 60 Shaft 430 likewise carries the grooved cam 434 fast thereon and the pin 435 fast in the upper end of vertical slide 436 enters the cam groove and is thus acted on by the movement of the cam. The downward 65 movement of connector 407 caused by the

curve of cam 411 from *a* to *b* allows the pawl 431 to drop back to catch a tooth of ratchet 433 and the upward move of the same connector caused by the contour of cam 411 from *b* to *f* makes the lever 429 give the 70 pawl its working stroke that moves the ratchet with the shaft 430 and its attached grooved cam 434. The nine teeth of ratchet 433 act as a tally for the step by step pitcher tilting inasmuch as the ratchet registers the 75 number of tilts. The slide is guided by the ways 437 while the lower end carries the guide pins 400 which have already been mentioned as on either side of the connector 399. Shaft 430 is supplied with a cord 80 drum 438 fast thereon and one end of the cord 439 is attached to the drum and after passing partially around it the other end is attached to the weight 440. The teeth of the ratchet 433 act upon the weighted hold 85 pawl 431' hidden from view by cam 434 and the flexible cord 441 leads from the hold pawl to the free end of lever 442 fulcrumed at 443 and provided with the pivoted roller 444 which follows the shape of the cam 445 90 fast on cam shaft 213. Flexible cord 446 is attached to pawl 431 at one end and the other end to the end of lever 442 with the result that during the rotation of the cam shaft 213 the lever 442 rises and by pulling 95 up the cords 411 and 446 raises both push and hold pawls and thus frees the teeth of the ratchet 433 from the restraint of both pawls so that the weight 440 can retract the shaft 430 and with it the parts fast thereon 100 until the end 447 of the slot in cam 434 comes up against the pin 435 and the retraction stops. Each downward movement of cam lever 409, caused by cam 411, will make the pawl 431 drop back to catch a 105 ratchet tooth while each pull will cause the pawl to move the ratchet 433 one tooth and the consequent intermittent rotation of cam 434 will force slide 436 downward so that the guide pins 400 will move pin 401 of 110 connector 399 farther and farther down in the slot 402 of lever 403 and it is evident that the farther the pin 401 is moved from the fulcrum 404 the greater will be the distance through which the connector 399 and 115 the rack 398 are moved. Therefore each cycle of movement of the cam lever 409 will cause the pitcher to tilt and then to return to vertical. During the use of any one pitcher each successive move of lever 409 120 gives a greater angular tilt to swivel plate 368 with a corresponding greater tilt of the pitcher. I have constructed ratchet 433 with nine teeth so that eight movements will cause eight increased tilts which will be sufficient to empty the pitcher. The slot in lever 403 in which pin 401 of connector 399 operates is so formed that when this lever is at its extreme left hand position the connector carrying the pins can be forced up 125 130

or down in the slot without materially moving the latter from the vertical. Cam 434 is provided with a cam point 448 which upon an additional or ninth movement of the ratchet 433 will contact with the end 449 of lever 450 fulcrumed at 451, the lever being held in operative position by the spring 452. The rigid connector 453 is freely attached to lever 450, extends upward, and is attached at 454 to lever 455 fulcrumed at 456 and the upper arm is forked at 457 to straddle wire 192' being able to actuate collar 457' fast on wire 192' which acts upon and actuates the sliding tooth 200 of gear 198. The result is that the ninth stroke of pawl 431 will cause the cam point 448 to actuate lever 450 and consequently start up the sliding tooth gear 198 which will cause cam shaft 213 to rotate with the result that cam 445 will move lever 442 and cause it to lift up the two pawls of ratchet 433 and allow weight 440 to retract shaft 430 and cam 434 back to normal; therefore the next pitcher brought into action will start pouring at the smallest tilt.

Pitcher shifter lever 367 is provided with a pin 367' which is positioned conveniently to contact the color car and thus prevent the pitcher lever from making its second swing toward the yarn cylinder during a pouring whenever by the exigencies of the pattern, the car stops at the magazine end of the drum during a pouring for an index skip, therefore in such a case the pitcher will spill the dye into the idly waiting car instead of passing across the car from end to end and possibly spilling a portion of the dye on the floor. See Fig. 9.

I will now describe the means for causing the mechanism associated with swivel plate 368 to grasp the pitcher on the magazine. The cam 458 is fast on cam shaft 213 (Figs. 1 and 2) and the cam lever 459 fulcrumed at 217 is actuated by the contour of the cam. The connector 462 freely attaches to lever 459, extends toward the magazine under the yarn cylinder and being pivoted at 464 to lever 465 fulcrumed at 466 actuates the lever and moves the slide 467 (Figs. 2 and 9) attached at 468 to the arm 469 of lever 465 (Fig. 9). The slide is guided in the bracket 470 attached to the end of track 144 and when the pin 471 is removed the slide can be swung about its pivot and laid on the floor out of the way of the operatives when they are stripping the yarn cylinder. Slide 467 is provided with the head 472 adapted to contact either 378' or 381' of the pitcher grasping device; an upward movement will cause it to push 378' upward and close the gripping fingers and pads onto the pitchers because a push on 378' will cause lever 377 to rotate until the pads 378 contact the bottom of the pitcher, and as 377 is fast on the shaft 375 the shaft is turned in its bearing

ing by the same upward thrust, carrying with it the ratchet sector 376 likewise fast on the shaft. Connector 388 transmits the angular movement of the ratchet section to the lever 387 fast on shaft 386, therefore pads 392 which are fast on the same shaft are rotated until they contact the outside of the pitcher which is standing on the shelf of the magazine. Pawl 381 is acted upon by the ratchet tooth against which it contacts by the contraction of spring 394 which is constantly trying to move both shafts in the opposite directions from the above described action, thus the pawl locks the elements in grasping position. The shelves of the magazine are cut away near each pitcher form 162 so that the rack 371 can have room to pass without touching the shelf.

A downward pull of 467 will unlock the grasping elements by causing head 472 to contact against the hooked end 381' of the connector 395' which has a head on its upper end and is attached at 395 to the arm 395^a formed integral with the pawl 381. A downward pull at 395 will rotate the pawl 381 on its pivot against the tension of spring 394 thus freeing the teeth of the ratchet sector from the holding effect of the pawl which allows spring 394 to contract and reverse the rotations of the two shafts 375 and 385 carrying the various holding pads to the unlocked position shown in Fig. 10 where they can not grasp the pitcher. Whenever the pitcher transfer lever swings over the magazine the head 472 of pusher 467 is between the contact points 381' and 378 of the pitcher grasping mechanism so that a working thrust of the pusher in either direction will actuate the grasping device.

The gears 398' and 370 (Figs. 9 and 26) when in mesh respectively with the two racks 397 and 371 of the bar 371^a constitute a planetary gear mechanism that keeps one gear in the same relative position as the other when one of them is fixed, the two gears being of the same pitch diameter. It is really identical with the planetary system of gearing shown for the magazine in Fig. 4 for the two racks represent one rack, being formed on the same bar, and a rack is known to be a gear with a radius of infinity so the rack corresponds to the intermediate gear 159 of the magazine. The result of this well known gear and rack arrangement is such that when the pitcher is grasped and then swung at the end of lever 367 to position A (Fig. 9) the pitcher is retained in the same vertical position it occupied when in position on the shelf of the magazine because the lever or anchor gear 398' is held from rotation. The tilting of the pitcher is accomplished by moving the rack 398 which rotates the gear 398' in its axis so that rack 397 is moved which causes a similar rotation of the top gear 370 in the same

direction because rack 371 is in mesh with it, and the pitcher grasping swivel plate 368 is fast to the rotating gear 370, rack 398 being actuated through the action of cam 411.

5 It will be noticed that the cam lever and connector for the pitcher transfer and tilting mechanisms are on one side of the color car track while the similar elements for the box transfer are on the other side of the

10 same track.

When the color-car is at the magazine end of the printing drum and a new color-box is being installed in the car it is evident that the car must stay there all the time that the

15 old box is being removed and the new one inserted, and therefore the end 127^a of color-motion dead stop lever 127 must be "up" all of the above mentioned time so as to keep the locking bolt 71 out of the seat 70 in com-

20 stantly revolving hub 65 because the car will stroke if the color-crank 67 becomes coupled up with the driving hub 65. Now it has already been explained that whenever a color change takes place either the jacquard,

25 through its forty-ninth hook, or the cam 434 which is moved into contact with lever 450 upon a ninth pitcher tilt movement, will operate the slide 193 so it holds the index pawl at zero position, keeps the yarn cylinder

30 stationary and pushes the sliding tooth 200 over into operative position so the cam shaft 213 will start revolving and the various levers and mechanism set in motion make the requisite change of color. However it has

35 also already been explained that the color-crank 67 will always stroke the car unless the index pawl lever 40 makes a full rearward stroke and by contacting and pressing down rear-dead stop lever 92^c cause the hook

40 126 to actuate dead-stop lever 127 and thus stop the color crank (Figs. 13 and 37) such mechanism constituting the primary color control.

It must be evident that holding the index

45 pawl lever at the zero point by means of slide 193 will allow the vertically oscillating hook 117 through the contraction of spring 125' to contact against and then pull trigger 128 down thus forcing the catch 132 away

50 from the dead-stop lever (Fig. 37) which will allow the contraction of spring 124 to pull the dead stop away from the abutting finger and cause the crank to start revolving. The primary color control device is out of

55 action while the slide 193 is holding the index pawl and therefore I have provided a secondary color motion control as illustrated in Fig. 37. I fasten a collar 473 to the connector 116 and arrange pawl 474 to contact

60 with the collar and push against it so that hook 126 (Fig. 17) may be drawn over toward dead-stop lever 127 against the yielding resistance of its spring 125' and either throw "up" the dead-stop lever, or keep it

65 "up" which will prevent the stroking of the

color-car. The pawl 474 is pivoted at 475 on lever 476 which is fulcrumed at 477 in bracket 476' (Fig. 3) attached to the frame of the printing drum and from the arm 478 extends the connector 479 to the arm 480 of cam lever 481 fulcrumed at 482 and actuated by the pivoted roller 483 following the contour of cam 484 fast on cam shaft 213 which is always set in motion by the sliding tooth gear 198. The

70 spring 485 keeps the roller 483 against the cam 484, the rise and fall of cam lever 481 causing pawl 474 to reciprocate, one rotation of cam 484 making the pawl move toward the right twice and causing it to dwell there

75 after the second stroke until the roller drops down into the depression 486 just as the cam shaft 213 comes to a stop. I have arranged a shield 487 forming a portion of arm 488 of lever 489 fulcrumed at 490 in the bracket

80 476' and the weighted arm 491 tends to keep down against the stop finger 492. The top of connector 493 is freely attached to shield 487, at 494 the lower end being freely pivot-

85 ed at 495 to lever 496 fulcrumed at 497 while

90 the arm 498 extends into the path of movement of the lifting finger 499 attached to sector gear 86 of the color motion mechanism.

Pawl 474 is provided with a lug 500 adapted to rest on and follow shield 487 and when

95 the weighted arm 491 is resting against stop finger 492 the shield 487 will be up thus keeping the working end of the pawl above the collar 473 so that it cannot contact with it and pull the hook 126 over to allow it to

100 actuate the color crank dead stop lever 127 and thus arrest the action of the color car. In Fig. 37 the connector 84 and rack 85 of the color motion mechanism are shown as

105 down, the crank 67 being at the lower dead center, therefore the color-car is away from the magazine end of the printing drum and as soon as slide 193 is actuated to hold the index pawl lever 40 at zero the downward

110 stroke of the hook 125 caused by the cam 123

115 will actuate trigger 128 because the pawl 474 cannot actuate collar 473 and the catch 137 will be forced away from the dead stop by the cam head of the trigger 128 (Figs. 16 and 37), the crank 67 will start to revolve

120 stroking the color-car to the magazine just as required. The rising of the rack 85 as the crank arm 67 revolves toward its top center causes sector gear 86 to move lifting finger 499 upward and as soon as it contacts and

125 raises the arm 498 of lever 496 the connector 493 will be depressed to pull down the shield 487 against the resistance of weighted arm 491. The collar is now exposed to the second working stroke of the pawl 474 occasioned by the cam roller 483 climbing up the curve 486' of cam 484 and the collar and connector 116 will be moved toward the right by action

130 of the pawl, thus forcing the head of the hook 126 over against the color-dead stop

127 and the depression of hook 126 which is timed to immediately follow the sidewise motion of the double hook 125—126 will pull down dead-stop 127 so that the contraction 5 of spring 133 will pull catch 132 forward with lip 131 (Fig. 16) extending over the lip 130 on the dead stop so that it will be held there with the working end 127' up in the path of the abutting fingers 78 of the 10 color stroking crank 67 and thus the motion of the color-car will be stopped just as it would be if either the primary or subsidiary color control had similarly actuated hook 126. Every additional time cam 123 on 15 constantly revolving shaft 58 forces the hook 126 downward it will simply contact against the depressed dead stop which is being retained down by the catch 137 because the long dwell 501 of cam 484 will cause pawl 20 474 to keep collar 473 and consequently rod 116 over to their right hand position and thus retain the hook 126 over against the color dead stop 127 long enough until the color-box changing device has performed all 25 of its functions after which, when the roller 483 drops into the depression 486 of the cam, the pawl will be retracted away from the collar to wait until cam shaft 213 is set in motion again. Meanwhile the connector 116 30 is left free to function with the primary color control independently of the secondary color motion control. The upward thrust of lever 442 caused by cam 445 raises rigid connector 516 attached to the cam lever at 517 35 the upper end of the connector being freely attached at 518 to the lever 519 fulcrumed at 520 the upwardly extending forked arm 521 of which straddles the wire connector 192' and contacts collar 522 fast on the wire, thus 40 moving it toward the right. This mechanism causes the wire 192' to retract the slide 193 to the right and out of the path of the index pawl lever every time the cam shaft 213 makes a revolution and the shaft never 45 revolves except when a color change is being made. The continued stroking of the color motion mechanism will cause the shield 487 to rise and fall idly as the lifting finger 499 lifts and drops the lever 496 because the pawl 50 will not stroke again until the primary color control has been rendered again inactive by pushing the slide 193 over to the left so as 55 to hold the index pawl lever 40 at zero.

The actuation of slide 193 to stop the 55 stroking of the index pawl will act upon the color car driving mechanism as though the index pawl had made a short skip so that the car will start up if at rest, or keep stroking if running. My secondary color control 60 will always stop the car at the magazine or keep it there if it was already so positioned when a color change was called for. The cam 484 always causes the pawl 474 to make two operative strokes and thus holds it to- 65 ward the right during the remainder of the

single revolution of cam shaft 213 during a color change and the co-action of the lifting finger 499 on sector gear 86 and its controlled shield with the pawl will assure that if the car is standing at the index end of the 70 yarn cylinder it will make one stroke and stop at the magazine, or if moving away from the magazine it will at once make a return stroke and stop there; also when moving toward the magazine it will stop 75 there, or if standing it will stay there. However if the car is standing at the index end of the yarn cylinder, or if it is moving in that direction when a color change is called for then it is evident that the car will make a 80 stroke toward the magazine while the yarn cylinder is standing still and in either case the color roller will lay a stripe of color against the yarn which might not be called for in the pattern; therefore it is necessary 85 to prevent the roller from contacting the yarn while the car is making this necessary positioning stroke for a color change. To accomplish this purpose I have placed a cam 90 522 (Fig. 41) fast on cam shaft 213 so that it will force down cam lever 523 fulcrumed at 524 by contacting the roller 525 pivoted at 526 into which fits a projecting pin 528 fast in the top of slide 529 seated in the bearing 530 the foot of which is attached to 95 the track 144. Normally the slide and cam lever are kept up by the expansion of spring 531 that encircles the upper part of the slide and abuts against the top of the bearing 530, the spring being compressed by the downward thrust of the slide. The lower end of slide 529 is provided with the pivoted roller 532 that is adapted to contact with the lug 533 (Fig. 40) forming a portion of the top 100 part 147 of the color car 142 whenever the slide is forced downward. This downward movement takes place whenever the cam shaft 213 starts revolving for a color change and will occur whether or no the color-car 105 is at the index end of the yarn cylinder. If the car is there then the roller 532 contacts lug 533 and forces the top of the car downward until the hook 534 pivoted at 533 on the lower portion of the car, extends above the surface 536 adjacent to the lug 533 so that 110 the contraction of spring 537 will move the hook over surface 536 and hold the top part of the car down after the withdrawal of the slide, and with it the color roller 146 which 115 is journaled thereon as in customary printing drum practice. If the color car is moving toward the slide 529, the lug 533 will contact the depressed roller 532 which is timed to reach its lowest position just before the color car gets to the extreme limit of its 120 throw and the same action takes place. The color roller 146 is thus retained down at a level such that the top of the dye covered roller cannot contact the yarn on the cylinder, consequently the stroke of the car up to 125 130

the magazine will not make a color impression on the yarn. Fig. 39 shows the car standing at the magazine end of the track and positioned by the lever 273 and 267 which action has caused the trigger end 538 of the hook to contact with and to force itself out by the stationary finger 539 which is shown as attached to the track, thus releasing the top of the color car and allowing it 10 to assume its normal position under the influence of the expanding spring 149.

The mode of operation of my automatic jacquard controlled mechanism for actuating the yarn cylinder and color-car has been 15 carefully and specifically described, pointed out and claimed in my pending application numbered 318,716 of the series of 1915 filed August 20, 1919 and therefore in this application I will describe their operation 20 quite briefly.

The pulley 2 is of the double friction clutch variety in common use on printing drums. The left hand side clutch (Fig. 1) when thrown in, actuates the automatic devices, while the right hand side acts to 25 rotate the yarn cylinder while the yarn from the spools 4 is being wound onto the surface of the cylinder. The yarn guide 7 is traversed across the face of the cylinder by 30 the conventional method as the cylinder revolves so the yarn will be laid one strand deep on its surface in coils or bights, the ending of one skein of yarn being arranged to reach the beginning of its neighbor skein. 35 Thus the cylinder will be covered with coils of yarn wound preferably from several skeins, and after printing each coil will be a duplicate of every other coil of the hank, for one filling of the cylinder for a printing 40 ing is known as a hank.

The annular positioning of the cylinder is predetermined by the jacquard controlled index wheel 27. The jacquard operates to set up the pins 30 of the index wheel once 45 for each revolution of the wheel. The index pawl lever 40 and pawl 41 are urged forward by the pusher 52 which oscillates somewhat more than half a circle, while the retraction of the pawl is made by the pull of 50 weight 49 and the pawl's rearward annular movements are checked at variable positions by the jacquard actuated pins that have been protruded behind it. Thus the working strokes of the index pawl give the yarn cylinder step by step movements of various 55 length according to the selective set-up of the index wheel 29 for the two are connected by shaft 12 and gears 38, 39 and 14. Longer skips than twenty-four ratchet teeth 60 of the index wheel are accomplished by causing the pawl to make more than one working stroke during which time the color car is stopped. The spring pin 64 of the index wheel is always brought to the zero point 65 by the pawl for it always checks the pawl

lever and its arrival there marks the finish of each revolution and the beginning of the next one for immediately the jacquard indicates and re-sets the pins of the index wheel from its predetermined perforated 70 pattern. Each protruded pin is retracted as it passes the zero point, so all the protruded pins are retracted during one complete revolution of the index wheel.

The color car operating mechanism is 75 automatically controlled by the set-up of the index wheel. When the index pawl is making movements less than twenty-four teeth in length the color-car cut-out is positioned so that the driving crank revolves uninterrupted but when a long skip is made then the dead stop lever end 127 is thrown up into the path of motion of the abutting finger 78 by the primary color control quite similarly to the action of the stop motion 80 on a punch press and upon contact the locking bolt 71 is revolved in its seat so that the crank arm is freed from its drive and the car will stop. The subsidiary color control rules the stoppage of the color car 85 through the actuation of lever 107 whenever the spring pin is to be brought to the zero position. A short skip made by the index pawl will automatically depress the dead stop 127 and allow the color crank to 90 start up and stroke the color car because normally the spring 125 will hold hook 125 over against trigger 128 so that on its regular downward stroke the hook 125 will depress the trigger and unlock crank 67 so it 95 will stroke the car.

The color car contacts the yarn cylinder only while the cylinder is at rest, and the cylinder is turned, or indexed, only while the color-car is out of contact with it, just 100 as in regular good hand controlled printing drum practice.

In the regular hand operated printing drum in use in this country and England the printer not only positions the yarn cylinder by hand and governs the stroking of the color car but he, or his assistant, changes the colors in the color car, pours additional dye into the box from time to time, and 110 wipes the scraper between changes of color, 115 all these functions being performed manually. In contra distinction to this my machine attends to these requirements automatically without attention from the operative who is busy setting up in proper sequence boxes and pitchers for other machines in their respective sub-stations on the shelves of other machines.

The operation of my automatic jacquard controlled multiple color printing drum is 120 as follows: The attendant sets up the magazine with the various colors placed in the boxes and the necessary pitchers for the additional dye placed in the spring cups and in the forms according to the predetermined 125 130

sequence decided upon for the best production of the required design, the lighter colors being positioned to be used first. The color-boxes will be equipped as per the carefully thought out plan giving the ideal widths of color-rollers for the several colors, the correct doctors for limiting the amount of color picked up by the rollers, etc., and after the yarn cylinder has been covered 5 with yarn the workman will run the loaded magazine on to the track up against the check roller 502 and connect up the weighted traction cord 168. He rotates the magazine until the shelves are correctly positioned 10 with the first color box in place to come up to operative position upon the first rotative move caused by the pawl 179 against the ratchet 177. He hooks up connector 185 which operates the rotation of the magazine, raises hinged member 233 and places 15 the sustaining foot 236 in the floor socket 239 so the lever and tongs of the color box motion will function to remove and replace the colors; he also hooks pitcher connector 20 232 onto rack 364, swings the pitcher grasping pusher 467 into place, connects the hook of the tongs connector onto the pin 257 and connects up the car positioning levers with 25 their connector 276.

He next turns the yarn cylinder around and slides hand turning shaft 15 into operative position with pinion 14 properly placed in mesh with the internal gear 12 of the cylinder so that the starting point on the 30 cylinder is substantially in line with the top of the main frame of the machine. He then pulls on the shipper handle for starting the automatic device. The jacquard perforated strip has been properly placed and 35 the yarn cylinder rises at once and indicates the set-up for the first forty-eight pins of the index wheel, at the same time the forty-ninth jacquard hook 192 is indicated, pushed to the left carrying with it slide 193 which latches down the index pawl thus 40 keeping yarn cylinder stationary and the left hand end of pusher rod 192' contacts with and pushes over the sliding tooth 200 in gear 198 so the constantly rotating gear 45 201 on crank shaft 58 meshes with sliding tooth 200 and starts up the sliding tooth gear and consequently the bevel gears and upright shaft 204, also the horizontal cam shaft 213. The empty color-car is at the 50 index end of the yarn cylinder as is always the case while stripping the cylinder of its freshly dyed yarn and therefore its top is at once forced down and locked there by the descending pusher 529 (Fig. 41) which 55 is actuated by cam 522 in which case the color roller if in place could not touch the yarn on the cylinder. The dead stop 127 that has been holding the color crank 67 stationary is released from its retaining 60 65 catch 132 as it always will be by reason of the index pawl lever not making a long skip so the normal downward stroke of hook 125 will depress trigger 128 so head 136 will contact with 137 of catch 132 and force it backward thus freeing 127 from the catch, 70 hence spring 124 can contract and depress end 127' which allows locking bolt 71 to rotate in its seat to connect up the crank and start the car on time toward the magazine end of the track where it stops. The box 75 lever starts from normal position E toward the incoming color car, because pawl 474 of the secondary color control on its second working stroke caused by the action of cam 484 contacts with collar 473 on rod 116 80 and pushes it toward the right (Fig. 37) thus pulling hook 126 over against dead stop 127 thus causing its immediate depression by the action of cam 123 and its locking down by the retaining catch 132 which action forces the working end 127' up into the path of the rotating abutting finger 78 of the color-car stroking crank and causes the subsequent stoppage of the color-car 85 drive. Pawl 474 could not thus contact with the collar 473 on its first working stroke because the color car was at the index end of the yarn cylinder with the stroking crank arm 67 on its low dead center, consequently lifting finger 499 was not contacting lever 90 498 and the shield 487 was "up," hence protecting the collar from the action of the pawl which will always stop the color motion as above described if it can contact the collar and move the rod 116 toward the 95 right. The primary or the subsidiary color control will similarly stop the color motion whenever either of them moves the rod in the same direction. The long dwell 501 of cam 484 will keep the pawl over toward 100 the right by thus retaining the rod 116 and the hook 126 will continue to be over against the dead stop where its vertical strokes will simply bring it down against 127 which is already held by the catch 132. As soon as 105 the color car stops at the magazine end of its track it is positioned by the levers 267 and 273 which are swung about their respective fulcrums by the action of cam 281 against lever 278 the motion being transmitted through the connector 276. The lever 273 swings in behind the car and forces it along the track 144 against the lever 267 and the cam is shaped to thus hold the car 110 in place by the levers until it becomes time 115 to release it for the first stroke of the car after a color box has been placed in it.

As soon as cam shaft 213 started to rotate the color change began, for all the cams that actuate the change are fast on that shaft. 120 The box shifting cam 222 stands idly in the position shown in Fig. 36 while the machine is doing the printing; so as soon as the shaft 213 and its cams begin to rotate, which occurs immediately after the sliding tooth 125 130

has been pushed into working position by the actuation of pusher rod 192' from the movement of the jacquard griffe, cam 222 turns in the direction of the arrow with 5 roller 224 rotating freely as the long dwell 222^a of the cam passes it thus giving time for the blank stroke of the color car which has been described above. As soon as the beginning of depression 222^b of the cam 10 reaches roller 224 the contraction of spring 218 causes lever 216 to turn clockwise (Fig. 36) on its fulcrum as the depression passes with the roller following the contour, the motion being transmitted through connector 15 227 and its rack 228 to the gear 229 and box shifting lever 231 which likewise turns clockwise, swings its free end from normal position E (Fig. 4) over toward the yarn cylinder to position F where its tongs make 20 a try to catch the color box but as there is no box there the tongs fail to encounter a box, therefore do not open and grasp one so that the return swing of the shifter lever 231 back to the magazine does not carry a 25 box to be deposited on the shelf of the magazine. The positioning of the car by the action of levers 267-273 also acts to uncouple the color roller from its driving motion when lug 294 on lever 273 contacts lever 30 285 at 285' and turns it so that the square coupling 288 is pushed away from the squared head of the axle of the roller leaving the color roll free to be carried away with the box. The same movements cause 35 the two wipers 302-303 moved by the same shafts to pass across the working or rubbing faces of the scrapers and clean them of any dye remaining from the last scraping. When the box shifter lever 231 and its tongs 40 240-241 reach the magazine they are in the position shown in the left hand dotted line in Fig. 4 and also in Fig. 21 in the last of which the cam point 248 is shown as directly under the V notch of the abutting surfaces 45 250-251 of the tongs into which it is thrust so as to force them open by means of the pressure of the lever 256 against the pin 255 in lever 259 fast on one end of shaft 246 which carries the double cam pointed 50 245 fast on the other end thereof; said pressure coming from rotating cam 262 on cam shaft 213 against lever 259 the resulting motion being transmitted by the connector 252 to pin 257 of lever 256 (Figs. 55 3, 20, 21, and 22). The opening of the tongs would allow the color box (if there had been one in the grasp of the tongs) to be left on the shelf in the yielding grasp of the spring clips 164, while the shifter lever 60 65 and tongs swung back to normal at E as the dwell 222^c reached the roller 224 and during the passage of the dwell past the roller the cam 215 acts on the lever 216 the motion being transmitted through connector 185 to the bar 184 of the magazine, resulting in a working stroke of the pawl 179 which turns the magazine clockwise (Fig. 6) so that the lowest shelf holding the first color box of the series will come up to and stop at mid-position where it can be reached by the 70 tongs which now descend, contact with the box open freely, as the end of lever 231 swings still nearer the shelf, until the tongs pass over the ends of the box then grasp it and swing it over placing it squarely in the 75 color car which is still waiting to receive it. All these various swinging movements of the lever and tongs are caused by the contour of cam 222. Cam 281 again actuates its lever and causes cam point 247 to force open 80 the tongs thus freeing the color box so that the final motion of cam 222 can cause box shifter lever to return to normal at E. As soon as the box is free from the tongs, the car positioner cam 281 lets up on its lever 85 allowing the two positioning levers 267 and 273 to swing clear of the box, the same action moves the wipers away from the scrapers, while the swing away of lug 293 from roller-disconnector lever 285 allows 90 spring 295 (Fig. 40) to contract causing the lever to move square coupling 288 over against the head 291 of the axle of the color pulley so that when the out-going stroke of the car revolves the pulley 284 the coupling 95 will likewise revolve until the opening in the coupling coincides with the head 291 and the continued contraction of the spring slides the coupling home causing the roller to revolve with the sheave and pick up a 100 supply of the color-dye in which its lower portion is immersed so it will leave a suitable stripe of color upon the yarn on the cylinder as soon as it contacts the yarn. 105 Meanwhile the pitcher shifter lever 367 has been in action for it moves to and away from the magazine nearly in unison with the similar movements of the box shifter lever 231. Cam 257 begins to revolve as soon as the sliding tooth 200 is pushed home and 110 constantly rotating gear 201 meshes with and starts up gear 198 with a result similar to the box shifter motion, however, the pitcher lever starts quite slowly toward the magazine so as to place the pitcher thereon 115 gently while the roller 359 on lever 358 is forced up the first elevation of the cam against the tension of spring 361 which action turns the lever clockwise (Fig. 26) thus moving connector 362 with rack 264 toward 120 the left which causes a similar rotating movement in gear 365 in mesh with the rack and pitcher lever 367 fast to the gear. The lever starts from normal position A (Fig. 9) and moves slowly to the magazine at B 125 arriving about the time that the box lever gets there at which position the head 472 of the grasper slide 467 is standing about midway of the contact points 381-381' just at the time the cam 459, which is rotating on 130

shaft 213 with all the other cams, begins to actuate lever 459 and the action is transmitted by connector 462 to lever 465 which in turn moves slide 467 attached freely to the 5 lever at 468. The grasping device at the top of lever 367 is locked as though it were holding a pitcher although as yet there is no pitcher in it so the cam action forces the slide downward so it will contact point 381' 10 and draw hooked connector 395' down with it causing pawl 381 of the grasping device to turn clockwise on its pivot because 395' is attached at 395 to the arm 395^a formed integral with the pawl. This action frees the 15 teeth of the ratchet sector 376 from the retaining action of the pawl allowing spring 394 to contract which causes shaft 368 to turn contra-clockwise because the top end of the spring is attached at 368 to the lever 20 which is fast on the shaft, therefore the pads 392 swing to the right being fast on the same shaft while the connector 388 transmits the motion to the ratchet sector which being fast on shaft 374 causes the shaft to turn clockwise 25 carrying with it the pads 378 so the grasping device is unlocked and opens (Fig. 10) and would leave a pitcher on the shelf of the magazine if the lever had been carrying one. Lever 367 is now moved under the influence 30 of the contour of cam 357 back to normal at A where it waits the rotation of the magazine, just as the tongs do, and then move once more to the magazine when cam 358 causes slide 467 to be pushed up so head 35 472 contacts 378' pushing it upward thus reversing the unlocking and opening action of the grasping elements described above with the result that pads 378 are swung up into contact with the bottom of the pitchers (if 40 there is a pitcher there) while the pads 392 swing down to contact the outside of the pitcher on either side of the handle. The finger 393 passed over the spout of the pitcher while lever 367 was swung into 45 grasping position and now is extending down into the inside and nearly contacting the inside wall immediately opposite the handle while the pads 379 have contacted the barrel down near the base. The spring 394 has contracted to click the working end of 50 the pawl into a tooth of the ratchet sector so when slide 467 moves back to its normal position shown in Fig. 9 the grasping device will be locked in place with the pitcher held 55 firmly enough to enable it to be tilted contra-clockwise far enough to spill all of its dye; lever 367 is now moved under the influence of cam 357 back to normal at A where it waits until about thirty strokes of the color 60 car has exhausted the supply of dye in the box to such an extent that additional dye must be poured from the pitcher into the color box of the moving car without stopping the stroking action of the color motion

just as would the printer's assistant under 65 similar conditions.

A pitcher is placed on the magazine in conjunction with a color box whenever additional dye is required for printing over and above the initial quota in the box. Each 70 time the car approaches the index end of its track 144 the finger 319 fast on the car contacts with cam arm 318 and forces upward weight lever 314 (Figs. 26 and 37^A). The various elements are positioned so that 75 the float supported wire 306, that registers the level of the dye in the color box, passes under the feeler 310 just prior to the lifting of the weight lever, thus the downward dip of the freed feeler will be arrested by its 80 contact with the float wire and the feeler or detector "feels" of the float supported wire while the oppositely extending tail 311 rises to a corresponding point. When thirty color stripes have been laid on the coils of 85 yarn on the cylinder the feeler drops to a point low enough to allow the escapement wire 320 to pass under the upwardly positioned tail 311 which allows the working end of pawl 322 to drop down onto the top of 90 constantly stroking slide 330. The first forward impulse of the slide follows immediately after the above described contact so tooth 340 impacts the pawl and forces it and its slide toward the right until the end of 95 the escapement wire in its swung down position is pushed to the right of the tail 311 (see Fig. 24). The return stroke of the car can be made immediately thus moving finger 319 away from the weighted lever which allows it to fall upon the feeler lever at 315 and force it down against supporting finger 316 which action raises the feeler 310 up, but the escapement wire 320 has been moved over to its normal working side of the tail 100 311 before the weight can thus force the tail down.

The feeler has now detected "low color" in the moving box, the escapement of the wire has caused the two slides 330—328 to 110 be coupled up by the pawl and the exhausted color-box is making a stroke toward the magazine where it must be replenished with dye without stopping its action and this operation will now be described. The 115 second forward impulse of slide 330 under the further influence of the contour of cam 331 fast on the constantly rotating shaft 58 now moves the two coupled-up slides farther to the right (Fig. 26). The first movement of slide 328 caused lever 327 to turn contra clockwise until the pin in the end of lever arm 345 reached the bottom of slot 348 in the lower end of connector 346 but does not pull on the connector, however the second movement of the slides causes the connector to be drawn downward turning lever 347, to which it is attached, clockwise so 120 125

that the arm 351 impacts against the end of cam 353 and slides it along the rotating shaft 58 on its feather key against the resistance of spring 355 until the cams 5 411—415 are longitudinally in line respectively with the rollers and levers 409—412 and 413—416. The sliding cams 331 and 353 are so timed on the shaft that this sliding movement occurs while the common 10 dwell surface 353' of the cam is just coming on the top so as to be in line with the two rollers, hence the cam will move over in time for the roller to sink down the incline of their respective cams so the contour of the 15 cams can produce the desired movements in the levers. As soon as the rollers enter the cam recesses, slide 330 is retracted to normal, but the sliding cam is retained in operative position because one or both of the 20 rollers are impacting against the side of the cam and retaining it in place, longitudinally of the shaft, until both cams have forced their rollers out on to the common dwell 353' whereupon spring 355 can expand and 25 move the cams over into normal as shown in Fig. 26 where it will wait until pushed over again by lever 347 the actuation of which comes from the indication of the feeler.

The action of the contour of cam 415 on 30 lever 413 is conveyed through connector 418 to lever 420 which is the secondary element of the compound lever 420—358 that shifts the pitcher levers 367. 358 acts as the primary mover to shift the grasping end of the 35 lever from normal at A to the magazine to leave a pitcher, back to normal, then back to the magazine to grasp the next pitcher and again to normal, and during these motions lever 358 is acting as a lever of the first class 40 with the load at 363, the force operating at 359 while the fulcrum is intermediate the two points. The down movement of the connector 418, as the roller and lever 413 run down the incline of the cam c—d (Fig. 45 26B) allows spring 361' to contract thus causing lever 420 to move contra-clockwise so that the fulcrum 360 of lever 358 moves to the right hand which through connector 362, rack 364 and gear 366 causes pitcher 50 lever 367 to swing toward the yarn cylinder as far as position C (Fig. 9) where it meets the incoming car and as the lobe d—e of cam 415 forces lever 413 upward the movement of the pitcher lever is reversed and 55 the pitcher that is held in the grasping device is retained over the moving car and follows it to the extreme of the stroke of the car, at which point the pitcher is at position D, and then again, as the car begins its re- 60 turn stroke toward the index end, the pitcher is swung back to C for the second time as the roller passes down to d' and then is returned to normal at A. During these movements the fulcrum of lever 358 is at the cen-

ter of the roller 359 which is resting on the 65 idle cam 357, the load is at 363 while the moving force is applied at 360 by the pull of the connector on lever 420. The spring 361 in all cases acts to move the pitcher toward the yarn cylinder while cams 357—415 in 70 time act to stretch the spring and move the pitcher toward the magazine.

The pitcher follows the motion of the moving car exactly as does the pitcher in the hand of the printer's assistant while he 75 is pouring additional dye into the box; and I will now describe how the pitcher is tilted so that dye will spill out of the pitcher into the box while it is following the moving car. The cam roller 412 of lever 409 drops 80 down the curve a—b of cam 411 at the time the pitcher is approaching the incoming car, so the connector 407 moves downward and allows spring 404' to contract so as to turn lever 405 contra-clockwise which causes connector 399 and rack 398 to move toward the right, causing both gears 398' and 370 to turn in the same direction as the lever 405 because the racks 397—371 are on the same 85 bar 371^a, hence the pitcher grasping device 90 is turned through an angle that will cause dye to pour out of the spout of the pitcher in a steady stream all the time the pitcher is following the moving car and when the pitcher reaches position C the second time 95 the cam incline b—f forces lever 409 upward which reverses the tilt of the pitcher, stops the flow of dye, and brings the pitcher back to vertical by the time it arrives at normal. The two gears 370—398' in conjunction with 100 the rack bar 371^a constitute a planetary system of gearing that assures that the pitcher will remain vertical unless the lower gear 398' is changed in position and it is changed as above described through the actuation of 105 cam 411. The lowering of connector 407 also lowers the connector 427 so that pawl lever 429 drops backward far enough to allow pawl 431 to click into the next rearward tooth of ratchet 433, consequently the 110 upward move of the two connectors impels the pawl lever to make its working stroke clockwise which rotates ratchet 433, shaft 430, slotted cam 434 and cord drum 438 resulting in the winding up of a portion of 115 the weight cord 439 and a partial depression of slide 436 with its two guide pins 400 which positions the pin 401 in the slot of lever 405. This action of cam 434 moves pin 401 farther away from the fulcrum 404 120 so that upon the next move of the lever the connector 399 will receive a greater motion and thus cause gear 398' to turn through a greater angle to give a larger tilt to the 125 pitcher. The cam 434 is shaped to accomplish the desired end of tilting the pitcher at a greater angle at each tilt as the liquid lowers in the pitcher so that practically a

definite quota of dye will be poured into the car at each tilt and finally upon the eighth tilt the last of the dye will flow out into the color box in the car. Slot 402 in lever 403 is shaped so that pin 401 can move from top to bottom of it without tilting the pitcher when standing at normal. Each succeeding tilt has wound weight cord and weight farther up, turned cam ear 448 nearer to contacting with lever 450 at 449 and now after the car makes another thirty color stripes the last quota of color is used up and the feeler indicates a ninth tilt for more color and the pitcher is made to follow the car and tilt although it is already empty; then, as the upward move of connector 407 moves the empty pitcher back to normal the upward move of connector 429 attached to 407 causes the pawl to turn the ratchet for the ninth time which results in the actuation of lever 450 by cam ear 448 in a contra-clockwise direction which draws connector 453 down thus turning lever 455 contra-clockwise so that its forked end 457 impacts against collar 457' fast on pusher rod 192' and moves it toward the left exactly in the same way and on the same time as the jacquard actuates the same rod for a color change. This action results in drawing over the slide 193, for it is attached to rod 192', just as though the jacquard had actuated its forty-ninth hook for a color change, so lug 193' gets over the index pawl lever 40 while it is at zero position and prevents it from being retracted by its pull weight, so it cannot get into a new working position, hence the primary color control is rendered inactive while the indexing of the cylinder is halted. However the move of rod 192 pushed the sliding tooth into place in gear 198 consequently constantly rotating gear 201 meshes with it and starts it and its train of bevel gears to rotating which causes cam shaft 213 to begin its revolution for a color change.

In this explanation it is assumed that the pattern being printed calls for more than the two hundred and seventy stripes of the same color that have been described as being applied, thirty being in the initial quota of color in the box and two hundred and forty being in the pitcher; therefore the next box and pitcher to be put into use must be of the same color which information was followed by the printer when setting up his magazine. As above described any ninth tilt will start a color change, so the car is positioned, the box, roller and pitcher transferred to their original places on the shelf of the magazine which now turns bringing a new box with the roller and a pitcher of the same color up into grasping position and they are transferred as above described ready for the next stroke of color which can not be made until slide 193 is moved back to normal so the index pawl can operate to control the position of the yarn cylinder and the stopping of the color car. Cam 445 on shaft 213 accomplishes this object as well as another important move. When shaft 213 approaches the end of its single revolution for it should be remembered that it makes but one at any one color change, the cam 445 contacts with roller 444 and raises lever 442 which likewise lifts rigid connector 516 causing lever 519 to turn clockwise so that the forked end 521 will contact collar 522 fast on rod 192' and push it back to normal, thus also pushing slide 193 back to its normal position which restores the primary color control to its duty of controlling the stoppage of the color car and positioning the yarn cylinder. The stoppage of the shaft 213 also leaves the color control with the roller 483 resting in the depression 468 of cam 501 so that the pawl 474 is forced back away from the collar 473 leaving the primary full control over the color motion. The raising of lever 442 by the cam 445 besides causing the retraction of slide 193 also draws up the two flexible connectors 441-446 which are respectively attached to the hold pawl and push pawl of the tilt increasing ratchet 433 and thus pulls both pawls away from the teeth of the ratchet so weight 440 can at once cause ratchet, shaft, and cam 434 to revolve backward to normal; thus the slide 436 is raised, carrying with it the end 401 of tilting connector 399 and the tilting device is restored to normal so that the first tilt of the new pitcher will be of the first scheduled angularity for a first pouring. It should be noticed that a rotation of cam shaft 213 for a color change whether by action of the jacquard or by means of the ninth pitcher tilt will always cause cam 445 to actuate the various elements to push slide 193 back to normal, and also raise the two pawls so the weight can bring the slotted cam back to normal, for it must be evident that a new pitcher must always be tipped to the first angle for its first pouring, and that a pitcher may be tilted any number of times up to nine, therefore the slotted cam must be set back to normal after a color change.

The various sub-stations for the boxes on the four magazine shelves are arranged to be interchangeable as regards boxes and pitchers, however when a pitcher is placed on a shelf then that set of four sub-stations that come into operative position during one complete rotation of the magazine, one on each shelf while at one longitudinal station, are for pitchers only although there may not be four pitchers (Fig. 7) and there is no stopping disk 505 for that longitudinal station, which is a pitcher station only, but instead the stopping disk is slipped along on its shaft and made fast thereon at the next station occupied by those color boxes that

- the pitchers work with. It should be noticed that the magazine in its longitudinal motion stops only at color box stations, and if there is a pitcher to act with a color box
- 5 then that traction shift of the magazine is twice as long as for a single color box station shift. The pitchers always come ahead of the boxes, *i. e.* are nearer the traction weight 172. The pitcher moving lever 367
- 10 is adapted to swing in between two adjacent color-boxes without impacting either box and in such a case it goes through its motions of grasping a pitcher without result because there is no pitcher there.
- 15 The dye drawn by the roller out of a box is limited to enough to make thirty stripes after which additional color is automatically poured in from a pitcher. This is particularly the case for ground colors where there
- 20 are comparatively long patches of the same color, because experience has shown that the color-roller will fail to pick up a sufficient amount of color if the supply is allowed to run too low and the result will be an uneven
- 25 shading that may be noticeable. However in many designs there are colors that appear in isolated places scattered over the pattern and in such cases a narrow color roller is used so that as many as fifty or more color
- 30 strokes can be taken from the original filling of the box without the addition of a new quota of color. As the spots of color are isolated from each other the eye of the observer could never match up the shade of a
- 35 spot having a slight paucity of color with one some feet away that received the full amount of dye. In such cases the float-supported wire 306 is not used but instead a false float wire 306' is clipped onto the side
- 40 of the color-box (Fig. 36) and as it does not change in position the feeler never indicates "low color" so fifty or even sixty color strokes can be made, all that are required by the design, after which the jacquard calls
- 45 the next color.
- When the first four sub-stations on the four shelves of the magazine have been turned into place one after the other in order, it will be found that the first notched
- 50 stop plate 505 (Fig. 7) fast on shaft 506 that is geared up to rotate in unison with the magazine will now be in such a position that during the next turn of the magazine the opening 511 in the stop plate will come
- 55 opposite check roller 502 and as soon as this occurs the pull of the traction weight 172 will cause the entire magazine to move longitudinally along the track 167 because the opening in the stop plate will allow it to
- 60 pass the check roller. The opening comes opposite the roller while it and the magazine are half turned and still turning, and therefore the shaft 506 will continue to turn and the next stop plate will check the magazine
- 65 by contacting against the check roller be-
- cause the opening in the second plate turns past the registering point of the roller before the weight 172 can draw the magazine up to the second plate or the second station, the opening in all the stop plates being in 70 line with each other.
- The printing will continue in the above described fashion until all the color boxes and pitchers have been used and when the last stripe of color has been laid the box 75
- 80 will be removed from the car, placed on the magazine and, as there is no other color box, the box-moving lever and tongs will go through an empty motion of placing another box in the car, the car will start off to the index end of the yarn cylinder, stop there, and the entire machine will be stopped in a conventional manner by action of the jacquard throwing off the shipper handle. This leaves the empty color car at the index 85
- 90 end of the cylinder as desired, the various connectors can now be disconnected and the magazine moved out of the way, the projecting and interfering levers and supporting frame laid on the floor, the cylinder strip- 95 ped of its yarn exactly as in usual practice and the cylinder re-filled with fresh yarn for the next printing.
- The primary, subsidiary and secondary color controls govern the stoppage of the 95 color car and I will now show how they differ. The primary color-motion control operates from the index pawl lever 40 which is positioned in its rearward moves by the jacquard projected pins of the index wheel. 100 An index skip of over twenty-four teeth accomplished by more than one full working stroke of the index lever will require the lever to contact the back dead stop lever 92' at each full rearward stroke which will 105 similarly actuate the hook 126 and force it over against the color-dead stop 127 and the next downward stroke of the hook 126 will raise the working end of the dead stop 127' and stop the color-car, while each succeeding full rearward stroke of the index pawl will act similarly to keep it stopped. Normally the color-motion crank 67 will rotate constantly and stroke the car for any length of index skip not exceeding twenty- 110 four teeth, the single exception being the subsidiary color control consisting of the arrangement whereby a check of the index lever by the spring pin may cause the hook 126 through the actuation of lever 107 115 (Fig. 29) to throw up the color dead stop lever end 127' and stop the movement of the driving crank.
- Fig. 37 illustrates the secondary color-control which controls the mechanism when 125 the primary becomes inactive and the car is supposed to be standing in Fig. 37 at the index end of the cylinder, while the jacquard has indicated for color box change as the index pawl pushes the spring pin to the 120
- 130

- zero position. The car was standing because the primary color-control had stopped it at the index end with crank 67 at the bottom center, and now, when the jacquard 5 pushes its forty-ninth hook 192 toward the left moving the lug 193' into the retractive path of the index lever 40, so as to retain the index pawl at zero and thus renders the primary color control inactive, it is evident 10 that the retension of the pawl at zero will have the same effect as though the primary color control was operating for a short index skip which always causes the color-car to start up and in this instance stroke toward the 15 magazine. The drawing shows that cam 123 has acted to depress the hook 125 releasing the color dead stop from retaining catch 137 so the contraction of spring 124 could depress dead stop 127 and the color crank is 20 upon the point of beginning to revolve to move the car toward the magazine. The car is required to be there to meet the approaching tongs because the movement of the forty-ninth jacquard hook has started 25 up the sliding tooth gear setting in motion the cam shaft 213 bearing the color-box moving cam 222. The rotation of cam shaft 213 with all of its cams fast thereon caused cam 522 to actuate the car looking down slide 30 529 (Fig. 41) which pushed down the hinged top part 147 of the color car so that hook 534 caught and held it in its depressed position, thus holding the color roller so low that it does not contact with and make a stripe on 35 the yarn on the cylinder while making this positioning stroke. Fig. 39 shows the automatic unlatching of the top of the car as the stop 539 contacts the tail 538 of the retain latch while the car is being positioned. 40 The cam 484 (Fig. 37) has actuated the secondary color motion pawl 474 but the shield 487 is "up" and thus the pawl failed to contact the collar 473 on the connector 116 and move it toward the right. If the pawl had 45 contacted the collar then the movement of the connector toward the right would have moved the hook 126 to contact dead stop 127 so that the color dead stop would not have been unlatched and the car would not have 50 moved to meet the color box tongs. So the object of the shield is plain; it is normally "up" and protecting the collar 473 when the car is at the index end of the cylinder; while the rise of the lifting finger 499 as the crank 55 67 revolves to the top center, thus stroking the car to the magazine end, will depress the shield so as to expose the collar to the action of the pawl when the car is at the magazine end. It is therefore plain that as the car 60 reaches the magazine end of the machine the shield is depressed, the collar is exposed and upon receiving the second working stroke of the pawl the crank that strokes the car is stopped. The pawl makes two working 65 strokes by means of the contour of cam 484 and then holds the hook 126 over against the color-dead stop lever 127 until the color-box moving device finishes its action and then the roller 483 drops into depression 486 of the cam 484 moving the pawl back to normal which leaves the connector 116 free to be acted upon by the primary or subsidiary color control mechanism as usual. The turning of cam shaft 213 always causes cam 445 to actuate the elements that push slide 75 193 back to normal.
- If the car is moving toward the index end, when the jacquard calls for a color change, the mechanism acts exactly as described above. However if the car be moving toward the magazine when the call for a color change comes, or if the car is standing there, then the shield will be depressed by the lifting finger 499 and the first working stroke of the pawl against the collar 473 will throw 80 the hook 126 over against the color dead stop lever 127 to throw it up for the incoming car, or keep it up for the standing car. The second working stroke of the pawl will also actuate the connector 116 to keep the 85 car at the magazine end and then the hook will be kept by the long dwell 501 of cam 484 against the color dead stop until just before the cam shaft 213 comes to rest. Thus the secondary color control will automatically take care of every case that may 90 arise which it should control. It should be understood that I do not confine myself to any specific form of printing machine simply because I have carefully described one good 95 design. I am the pioneer inventor in printing machines in which the color is changed automatically and therefore am entitled to the broadest type of claims and to the most liberal interpretation that can be applied 100 thereunto.
- Modifications may be made in practice without departing from the principle of construction herein disclosed.
- Having thus described my invention what 110 I claim as new and desire to secure by Letters Patent is:
1. In combination, color applying mechanism, a source of color supply therefor, jacquard means for automatically transferring 115 color from said supply to said mechanism, and means to actuate said mechanism.
  2. In combination, color-applying mechanism, a magazine delivering various colors interchangeably to said mechanism, jacquard 120 means for automatically controlling the operation of said magazine, and means acting in time with said last-named means for actuating said mechanism.
  3. In combination, color-applying mechanism, a magazine delivering various colors interchangeably to said mechanism, and jacquard means for automatically actuating 125 said mechanism between the color-delivering intervals.

4. In combination, color-applying mechanism, a source of color supply therefor, color-transfer mechanism adapted to deliver color to said mechanism, jacquard means 5 for automatically actuating said color-applying mechanism, and means for automatically timing the operation of said color transfer mechanism. 70
5. In combination, color-applying mechanism, a source of color supply, color transfer mechanism obtaining color from said supply, means whereby said color transfer mechanism may feed color to said color-applying mechanism, jacquard means for 75 automatically actuating said transfer mechanism and means for automatically actuating said color-applying mechanism. 80
6. In combination, color-applying mechanism, a source of color supply, a color transfer mechanism obtaining color from said supply, means whereby said transfer mechanism may automatically deliver a given quota of color to said color-applying mechanism, and jacquard means for automatically 85 actuating said color-applying mechanism. 90
7. In combination, color-applying mechanism, a source of color supply, jacquard means for automatically timing the interval of continuous operation of said mechanism, color-transfer mechanism receiving color from said source of color supply, said transfer mechanism when actuated adapted to deliver a definite quota of color to said mechanism, and means controlled in time 95 with said color-applying mechanism for governing the repeated operation of said transfer mechanism. 100
8. In combination, a magazine adapted to deliver a series of colors consecutively, color-applying mechanism fed from said magazine, automatic means for varying the duration of continuous operation of said color-applying mechanism, and means controlled predeterminedly for timing the order of color feeding from magazine to color-applying mechanism. 105
9. In combination, a magazine adapted to control the delivery of a series of colors, color-transfer mechanism movable from 50 said magazine up to a definite point, color-striping mechanism movable from and toward said mentioned point, and means for automatically controlling the repeated operation of said color-transfer mechanism. 110
- 55 10. In combination, color-applying mechanism making a scheduled number of stripe laying strokes, a source of initial color-supply, color-transfer mechanism delivering a definite quota of color to said mechanism, and means whereby said color-transfer mechanism may make a scheduled number of color deliveries to said color-applying mechanism. 115
- 60 11. In combination, jacquard controlled color-applying mechanism making a sched- 120
- uled number of impressions, a source of initial color supply, said color applying mechanism movable toward said source of color supply, and automatic means movable from said supply source toward said color applying mechanism for delivering color thereto. 125
12. In combination, a color box, means for impelling the same, jacquard controlled mechanism for removing said box from said means and means for actuating said mechanism. 130
13. In combination, means for conveying color boxes a magazine containing various color boxes, jacquard controlled means for delivering a color box from said magazine to said conveying means, and automatic mechanism for actuating said last named means to return the delivered color-box back to said magazine. 135
14. In combination, a magazine containing color-boxes, means for *seriatim* moving said magazine step by step to present a color-box thereon, jacquard controlled color-applying mechanism, and means taking hold of a color-box from said magazine and feeding it to said color-applying mechanism, said last-named means being capable of returning a color-box from said mechanism to said magazine. 140
15. In combination, a magazine containing color-boxes, means for moving said magazine to present each of its color-boxes, jacquard controlled color-applying mechanism, color-box delivery mechanism plying between said magazine and said color-applying mechanism, and means carried by said delivery mechanism for taking color-boxes from said magazine and delivering same to said color-applying mechanism. 145
16. In combination, jacquard controlled color-applying mechanism, means for moving said mechanism, an initial source of color-supply, means for delivering color from said initial source to said mechanism, and means for automatically replenishing said mechanism. 150
17. In combination, jacquard controlled color-applying mechanism adapted to carry color-boxes, color-box gripping means for taking hold of a color box to deliver same to or from said mechanism, and a holder for color-boxes actuated to receive the color-box delivered by said means from said mechanism. 155
18. In combination, jacquard controlled color-applying mechanism adapted to carry color-boxes, color-box gripping means capable of seizing and holding a color box, a magazine containing a series of color-boxes, automatic means for directing said gripping means in movement toward said magazine, and automatic means whereby said gripping means may discharge color-boxes upon said mechanism. 160

19. In combination, color-applying mechanism adapted to carry color-boxes, a magazine holding color boxes of predetermined uniform contents, pitchers also carried by 5 said magazine alongside the color boxes, said pitchers containing color dye, means for automatically carrying color-boxes and pitchers from said magazine to said color-applying mechanism, and means for automatically emptying the contents of any of said 10 pitchers into a color box upon said mechanism.
20. In combination, color-applying mechanism carrying a color-box, means for automatically filling said color-box, and means 15 for automatically removing the color-box from said mechanism.
21. In combination, color-applying mechanism carrying a color-box, means movable 20 into position adjacent to said mechanism to fill said color-box, and means for automatically replacing an exhausted color-box by a filled color-box.
22. In combination, color-applying mechanism carrying a color-box, a pitcher operable 25 adjacent to said color-box to fill it with color, and means for removing said color-box from said mechanism and carrying said pitcher with it.
- 30 23. In combination, color-applying mechanism carrying a color-box, a color-filler therefor, means for automatically actuating said color filler to deliver color to said mechanism, a magazine adapted to receive said 35 color-box and filler therefor, and means for actuating said last-named means.
24. In combination a magazine having a series of stations holding color-containing 40 boxes and color-containing pitchers, color-applying mechanism, means for selectively delivering color-boxes to said mechanism, and means whereby pitchers may automatically accompany said color-boxes.
25. In combination, a magazine having a 45 series of stations holding color-containing boxes and color-containing pitchers, color-applying mechanism receiving boxes from said magazine, means for delivering pitchers from said magazine to a position adjacent to 50 said mechanism, and means for automatically transferring the contents of said pitcher to the color-box adjacent to it.
26. In combination, a magazine having a 55 series of stations holding color-containing boxes and color-containing pitchers, color-applying mechanism, color-box transfer mechanism receiving color-boxes from said magazine and delivering them to said mechanism, and means carried by said transfer 60 mechanism for carrying pitchers out of said magazine to said color-applying mechanism.
27. In combination, a magazine holding 65 color-containers and color-containing reservoirs, means for impelling color containers in a defined circuit, said magazine having stations for holding said container and reservoirs, means for automatically moving said magazine to present the several stations, and means for selectively delivering reservoirs with said color-containers. 70
28. In a device as described, in combination, a jacquard controlled color car receiving color containers, and means for automatically replenishing said car with fresh color containers. 75
29. In combination with jacquard controlled color-applying mechanism, a reservoir carried by said mechanism, and means for automatically and periodically spilling color dye into said reservoir. 80
30. In combination, with jacquard controlled color-applying mechanism, a reservoir carried by said mechanism containing a working level of color-dye therein, and means for automatically raising the level of 85 said dye in said reservoir.
31. In combination with jacquard controlled color-applying mechanism, a reservoir carried by said mechanism containing a working quantity of color dye therein, and 90 automatic means for periodically adding quantities of dyes equal to the amount consumed.
32. In combination with color-applying mechanism making stripe laying strokes, a 95 reservoir carried by said mechanism and containing coloring dye therein, jacquard mechanism for timing the strokes of said mechanism, and means operable at the conclusion of a plurality of said strokes for re-filling said reservoir.
33. In combination with jacquard controlled color-applying mechanism making stripe laying strokes, means for feeding color-dye to said mechanism periodically, 100 and means for controlling said first-named means between intervals of said stripe laying strokes. 105
34. In combination, jacquard controlled color-applying mechanism making stripe laying strokes, color-dye delivery mechanism associated therewith, and means controlling the operation of said mechanisms. 110
35. In combination a coloring device having provision for receiving interchangeably different colors, a yarn holder engageable by said device successively during each operation, and means for automatically and predeterminedly reoperating said coloring device for each new color received by it. 115 120
36. In combination, a coloring device having provision for receiving interchangeably different colors, means for timing the order of change of said colors, a yarn holder engageable by said coloring device periodically, and automatic jacquard controlled mechanism adapted to control the intervals of engagement between said coloring device and said yarn holder. 125
37. In combination, a coloring device hav- 130

ing provision for receiving color-dye, a series of vessels containing different colors, each of said vessels being consecutively adapted to deliver dye to said coloring device, and mechanism adapted to time the actuation of said vessels.

38. In combination, a coloring device having provision for receiving and holding color-dye, a series of vessels containing 10 colors, mechanism whereby said vessels are interchangeably shifted into color-delivery position to supply said device, and means for automatically controlling the intervals of receipt of color dye by said coloring 15 device.

39. In combination, a coloring device having provision for receiving and holding color-dye, means for holding a series of dye-containing vessels, means moving toward 20 said other means to receive vessels, means for automatically effecting a transfer of dye from vessel to coloring device, and a yarn-holder toward which said device moves in order to lay color-stripes thereagainst.

40. In combination, a coloring device having a fore and aft movement, a yarn holder toward which said device moves to apply color, a source of color-supply toward which said device moves to receive color, and means 30 for automatically substituting one color for another at the source of color supply.

41. In combination a coloring device, a source of color supply, means taking color at the source and delivering it to said coloring device, means for automatically changing the colors at the source, and means for automatically controlling said coloring device during the color-change interval.

42. In combination, color-transfer mechanism having a color-receiving and a color delivery position, a coloring device supplied from said transfer mechanism, color-holding mechanism having provision for changing colors, and means for automatically delivering color from said color-holding mechanism to said color-transfer mechanism.

43. In combination, a coloring device, color-delivering mechanism movable adjacent said coloring device, and color-change 50 mechanism associated with said other mechanism.

44. In combination, a coloring device, color-delivering mechanism movable so as to supply said device with color, means for 55 automatically actuating said mechanism, a color holder having various colors, means operable to transfer any color from said holder to said color delivering mechanism, and means for automatically actuating the 60 last-named means.

45. In combination, a coloring device, a color-box supplying said device with coloring dye, means supplying said color-box with dye, means for automatically replacing 65 the color-box, and means acting in time with

said other means for predeterminedly actuating said first-named means.

46. In combination, a coloring device, a color-box supplying said device with coloring dye, means for supplying said color-box 70 with color-dye, means for automatically delivering said box and means together, and means whereby said box and means may be delivered separately.

47. In combination, a coloring device, a 75 holder containing color vessels filled with dye, means for automatically positioning said holder so as to consecutively present a different vessel, means for actuating said coloring device to lay a variably predetermined number of stripes, mechanism for transferring each vessel presented to said coloring device, certain of said vessels containing different colors, and means for re-operating said coloring device upon the presentation of any of said mentioned set of different color vessels. 85

48. In combination a jacquard controlled coloring device operated to make a predetermined number of stripe laying strokes for 90 each color received, means for automatically delivering color to said coloring device, and means for automatically measuring a definite quota of color delivered to support the operation of said coloring device. 95

49. In combination, a coloring device, a holder containing color vessels, means for automatically positioning said holder so as to consecutively present a different vessel, means for selectively delivering said vessels 100 to said coloring device, and means operated in accordance with a schedule for actuating said last-named means, said holder acting in time with said last-named means.

50. In a device as described, in combination, a movable jacquard controlled color-car, a magazine, and means stationed at the magazine and following the movements of said car designed to deliver coloring matter thereto. 105

51. In a device as described, in combination, a magazine, a color-car movable to a position proximate to said magazine, and means for predeterminedly actuating said color car. 110

52. In a device as described, in combination, a magazine, a jacquard controlled color-car movable to a position proximate to said magazine, and means interposed between said color car and said magazine and adapted to automatically transfer dye from magazine to color-car. 120

53. In a device as described, in combination, a dye holding magazine, a jacquard controlled color-printing device positionable 125 opposite said magazine, and means for emptying said magazine of dye to supply said mechanism.

54. In a device as described, in combination, a dye-holding device, jacquard con- 130

trolled printing mechanism emptying said device intermittently, dye-feeding mechanism adapted to deliver dye from said means to said color-printing mechanism, and 5 means controlled by said printing mechanism for actuating said feeding mechanism.

55. In a device as described, in combination, jacquard controlled color-printing mechanism, means for automatically supplying 10 said mechanism with dye, and a dye holding container periodically operated to feed said means with dye.

56. In a device as described, in combination, color-printing mechanism, a dye-holding 15 vessel, said color-printing mechanism moving together with said vessel, and means controlled by said mechanism as it moves for discharging dye from said vessel to said mechanism.

57. In a device as described, in combination, color-printing mechanism, a series of 20 dye-holding vessels, means for movably supporting said vessels, means for automatically picking vessels from said supporting means 25 and moving them toward said color-printing mechanism, and mechanism for discharging the dye from the respective vessels upon said mechanism.

58. In a device as described, in combination, color-printing mechanism, a dye-containing 30 vessel, a shelf for the latter, a carrier for said vessel, means mounted on said carrier for gripping said vessel, means mounted on said carrier for turning said vessel to discharge its contents, means for automatically moving said shelf opposite 35 said gripping means, and means moving said carrier over said mechanism and controlling said vessel turning means.

40 59. In a device as described, in combination, color-printing mechanism, a dye-holding vessel, means for automatically bringing said vessel over said mechanism, and means for turning said vessel as the latter reaches 45 its last-named position.

60. In a device as described, in combination, color-printing mechanism, a dye-holding vessel, means supporting said vessel tiltably, means for actuating said dye-holding 50 vessel to tilt it, and means acting in time with said last-named means and positioning said supporting means over said mechanism.

61. In a device as described, in combination, color-printing mechanism, a dye-holding vessel, means for shifting said vessel vertically in line with said mechanism, means for shifting said vessel longitudinally to a position over said mechanism, and 55 means for automatically coördinating the action of said first and second named means.

62. In a device as described, in combination, color-printing mechanism, dye-holding vessels, means for interchangeably position-

ing the respective vessels in line with said mechanism, means acting in time with the last-named means for positioning the respective vessels over said mechanism, and means for automatically causing said vessels to pour dye upon said mechanism. 65 70

63. In a device as described, in combination, color-printing mechanism, a series of dye-holding vessels, a common carrier therefor, a conveyer for any of said vessels, means for automatically bringing said conveyer and 75 mechanism together, and means acting in time with said last-named means for discharging the contents of said vessel upon said mechanism.

64. In a device as described, in combination, a dye-containing vessel, a support therefor, a color-car movable into a position adjacent to said support, means for taking hold of said vessel and movable in the direction of said car, and means for automatically 80 positioning said vessel to discharge dye into said car as the latter nears said support. 85

65. In a device as described, in combination, a dye-containing vessel, a jacquard controlled color-car, means whereby said color-car and said dye-containing vessel may 90 come together, and means for automatically discharging dye from said vessel into said car as they come together. 95

66. In a device as described, in combination, a dye-containing vessel, a jacquard controlled color-car, means whereby said color-car and said dye containing vessel may come together, said vessel adapted to move 100 in the same direction as said color car, and means for automatically emptying said vessel as both move.

67. In a device as described, in combination, a dye containing vessel, means for 105 movably supporting said vessel, a jacquard controlled color-car adapted to move in the direction of said means, and means for causing said vessel to discharge its dye into the incoming car. 110

68. In a device as described, in combination, a reciprocating dye containing vessel, means for movably supporting said vessel, a vessel tilter, a color car adapted to meet said vessel, means for actuating said tilter 115 to discharge dye from said vessel into said color-car, and means for actuating said first-named means to move it as the vessel tilts.

69. In a device as described, in combination, a dye containing vessel, means for 120 movably supporting said vessel, a reciprocating color car, said vessel supporting means and said color-car adapted to move toward each other, a vessel tilter, means for actuating said tilter, and means timing said 125 last-named means to act as said mentioned means and said color-car move toward each other.

70. In a device as described, in combination, a dye-containing vessel, a color-car movable in the direction thereof, means for carrying said vessel over said color-car, and 5 means for automatically and periodically turning said vessel to empty its contents into said color-car. 65
71. In a device as described, in combination, a color-car, a dye containing vessel, 10 means for moving said vessel toward said color-car, means for turning said vessel to dye-discharging position, and means controlled by said color-car for simultaneously actuating said first and second-named means. 70
- 15 72. In a device as described, in combination, a reciprocating color-car, a dye-containing vessel, mechanism for positioning said vessel over said color car, an actuator for said mechanism, and means controlled 75 by said color-car for starting said actuator. 80
- 20 73. In a device as described, in combination, a color-car, a dye-containing vessel, a movable carrier therefor, means moving said vessel toward said color-car, an actuator 25 for said means, motion-transmitting mechanism from said actuator to said last-named means, and means controlled by said color-car for setting said actuator. 90
- 25 74. In a device as described, in combination, a color-car, a dye-containing vessel, 30 means for carrying said vessel to meet said color-car, said means causing said vessel to follow the movements of said color-car, means for turning said vessel to tilt it 35 whereby its contents may be discharged, means for controlling the tilt of said vessel, and means controlled by said color-car for timing the operation of said second-named means and said tilt-controlling means. 95
- 40 75. In a device as described, in combination, a color-car, a dye-containing vessel, means for carrying said vessel to meet said color-car, means for actuating said other means, means whereby said vessel may repeatedly supply said car with dye, and 45 means controlled by said actuating means and adapted to actuate said last-named means. 100
- 50 76. In a device as described, in combination, a color-car, a dye-containing vessel, color-printing mechanism, a holder for said vessel adapted to tilt in order to discharge dye into said color-car, a regulator controlling the tilting action of said vessel, and 55 predetermined means for timing the operation of said regulator. 105
- 60 77. In a device as described, in combination, color-printing mechanism, a reciprocating dye-holding vessel adapted to supply 65 said mechanism with dye, check-controlled mechanism adapted to operate and reoperate said dye-holding vessel, and means for automatically positioning the color car relatively to said vessel to receive dye. 110
78. In a device as described, in combination, jacquard controlled color-printing mechanism, a dye-holding vessel adapted to pour dye upon said mechanism, and means for periodically operating said dye-holding vessel. 115
79. In a device as described, in combination, color-printing mechanism, a dye-holding vessel adapted to pour dye upon said mechanism, means for variably tilting said vessel periodically, and means for coördinating the operation of said mechanism and said vessel. 75
80. In a device as described, in combination, color-printing mechanism, a removable dye-holder in said mechanism, a dye-holding pitcher adapted to pour dye into said holder, and means for automatically transferring said dye holder and said pitcher from said dye-holding mechanism. 80
- 85 81. In a device as described, in combination, color-printing mechanism, a reciprocating dye-holder movable over said color-printing mechanism, means for automatically upsetting said dye-holder to discharge dye therefrom, and means for automatically impelling said mechanism to a position to receive dye therefrom. 90
- 90 82. In a device as described, in combination, a color car, a pitcher containing dye, means for tilting said pitcher to pour dye into said color-car, means for carrying said pitcher into position to reach said color-car, and means for automatically retracting said pitcher from dye-pouring position. 95
- 95 83. In a device as described, in combination, a color-car, a dye-containing pitcher, a carrier for said pitcher, means carried by said carrier for releasing the pitcher, means on said carrier for tilting said pitcher, and mechanism to increase the tilting of said pitcher. 100
- 100 84. In a device as described, in combination, pitcher positioning mechanism, motion transmitting means therefor, a color car containing dye, and a dye feeler for 110 said car adapted to actuate said means.
- 105 85. In a device as described, in combination, pitcher moving mechanism, means transmitting motion to said mechanism, intermittent motion receiving means actuating the other means, and means for automatically controlling the intervals of operation of said motion receiving means. 115
- 110 86. In a device as described, in combination, pitcher positioning mechanism, means for automatically actuating said mechanism, jacquard controlled color-printing mechanism, and means controlled by said last-named mechanism and adapted to time 120 said actuating means. 125
- 115 87. In a device as described, in combination pitcher positioning mechanism, a periodically actuatable movement controller for

said pitcher mechanism, a continuously operable actuator for said starter, and means for coupling said actuator onto said movement controller.

- 5 88. In a device as described, in combination, pitcher positioning mechanism, a color-car containing dye, a feeler for said dye in said car, a source of motion, a motion receiving member in advance of said source of motion, a coupling controlled by said feeler and effecting engagement between said source of motion and said member, and means actuated by said member for operating said pitcher positioning mechanism.
- 10 89. In a device as described, in combination, pitcher positioning mechanism, means for operating said mechanism, means for predeterminedly timing the other means, and a disconnectible member serving to couple both means together.

15 90. In a device as described, in combination, pitcher positioning mechanism, motion transmitting mechanism therefor, means actuating said motion transmitting mechanism, a primary source of motion for said actuating means, a color-car, and means controlled by said color car for coupling said actuating means and said primary source of motion.

20 91. In a device as described, in combination, a reciprocating pitcher shifter, means for operating said shifter, a color-car, and a timer for said means controlled by said color-car.

25 92. In a device as described, in combination, a pitcher shifter, a periodically operating actuator therefor, a continuously operating stroker for said actuator, color-printing mechanism and means controlled by said mechanism for connecting said actuator and stroker.

30 93. In a device as described, in combination, a pitcher shifter, means for actuating said shifter, means for periodically cutting out the operation of said actuating means, color printing mechanism, and means controlled by said mechanism and adapted to time said last-named means.

35 94. In a device as described, in combination, motion transmitting mechanism, motion timing mechanism, motion regulating mechanism, a color car controlling said motion timing mechanism, a color-dye deliverer operated by said motion regulating mechanism, and means connecting said regulating mechanism and said motion transmitting mechanism.

40 95. In a device as described, in combination, a pitcher tilter, a pitcher positioner, color-transfer mechanism, and means controlled by said color transfer mechanism and adapted to control said pitcher tilter.

45 96. In a device as described, in combination, a pitcher tilter, a pitcher positioner, means for actuating said pitcher tilter,

means for actuating said pitcher positioner, and means for simultaneously controlling the operation of said tilter and positioner.

50 97. In a device as described, in combination, a pitcher tilter, a pitcher positioner, a primary and supplementary control of said tilter, and a primary and secondary control for said positioner.

55 98. In a device as described, in combination, a pitcher positioner, cam controlled means for actuating said positioner, and a supplementary means of actuation for said pitcher positioner.

60 99. In a device as described, in combination, a pitcher positioner, means for actuating said positioner to move a predetermined distance, means for causing said positioner to move a still farther distance, and separate mechanisms for causing said two last-named means to act in time.

65 100. In a device as described, in combination, a pitcher positioner, means for actuating said positioner over a predetermined distance, and means for increasing the distance of travel of said positioner.

70 101. In a device as described, in combination, a pitcher positioner, a pitcher tilter, said positioner and tilter movable normally over definite paths means for increasing the distance of travel of said pitcher positioner, means for increasing the distance of travel of said pitcher tilter, and mechanism causing said two last-named means to act in time.

75 102. In a device as described, in combination, a pitcher positioner, a pitcher tilter, means for operating said positioner in unison with said tilter, and color-printing mechanism controlling said means.

80 103. In a device as described, in combination, a reciprocating color-car, a pitcher positioner, mechanism for moving said color-car up to the initial point of reciprocating movement of said positioner, and means for causing said positioner to follow the movement of said color-car.

85 104. In a device as described, in combination, a pitcher positioner, a reciprocating color-car having a defined path of movement, mechanism giving said positioner a defined path of movement, overlapping that of said color-car, and means for actuating said color-car.

90 105. In a device as described, in combination, a pitcher positioner, having a pitcher receiving and a pitcher pouring traverse, and mechanism for actuating said pitcher positioner.

95 106. In a device as described, in combination, a pitcher positioner having a pitcher receiving and a pitcher-pouring traverse, and a color-car movable with said positioner during its pitcher-pouring traverse.

100 107. In a device as described, in combination, a pitcher positioner, a color car mov-

110

115

120

125

130

able in a defined path, means controlled internally of said color-car for actuating said positioner, said positioner also having provision for emptying said pitcher, and means 5 also controlled by said color-car for actuating said positioner to empty said pitcher.

108. In a device as described, in combination, a pitcher carrier, a jacquard controlled color car running toward said pitcher carrier, and means for moving said pitcher carrier in the direction of said color-car.

109. In a device as described, in combination, a pitcher carrier, a color-car, jacquard controlled mechanism operating said color-car during a definite period of operation continuously, said color car adapted to reach said pitcher carrier periodically, and means for predeterminedly urging said carrier to follow the movement of said color-car.

110. In a device as described, in combination, a pitcher carrier, means for reciprocating said carrier, a color-car, means for reciprocating said color-car, and means timing both of the last-named means so as to cause 25 said color-car and carrier to meet.

111. In a device as described, in combination, a color-car, a pitcher positioner, a color-car positioner and means actuating said color-car positioner and controlling 30 said pitcher positioner.

112. In a device as described, in combination, a pitcher carrier, a color-car a positioner therefor, means actuating said color-car positioner, and means actuating said 35 pitcher carrier positioner in time with said color-car positioner.

113. In a device as described, in combination, a color-car, jacquard controlled means for moving said color-car, a dye holder 40 traveling with said color-car, continuously operating mechanism for actuating said color-car, and periodically operated mechanism for actuating said dye holder.

114. In a device as described, in combination, a color-car, a movable dye holder, means stroking said dye holder back and forth, means stroking said color-car back and forth, both of said means acting to allow said dye holder and color car to meet, 50 and mechanism adapted to cause said dye holder to spill dye into said color-car.

115. In a device as described, in combination, a jacquard controlled color printing mechanism means for carrying dye thereto, 55 and periodically operable means adapted to actuate said means.

116. In a device as described, in combination, a jacquard controlled color printing mechanism, means for delivering dye thereto, and means controlled by said mechanism for actuating said means.

117. In a device as described, in combination, a shelf, an arm movable from an upright to an inclined position over said shelf 65 and adapted to take a pitcher from said

shelf, and means for returning said arm to upright position.

118. In a device as described, in combination, a pitcher carrying arm, a color-car, pitcher tilting means on said arm, means 70 controlled by said car for urging said arm toward it, and cam-controlled means for actuating said tilting means.

119. In a device as described, in combination, a pitcher carrying arm, means urging 75 said arm to swing in a vertical plane, a color-car, means moving said car in a horizontal plane, means causing said arm and color-car to approach each other, and means operated in time with the last-named means for turning said pitcher.

120. In a device as described, in combination, a pitcher carrying arm, a main motion transmitter for said arm, a secondary motion transmitter for said arm, color-printing 85 mechanism, means controlled by said mechanism adapted to actuate said main motion transmitter, and jacquard controlled means for actuating said secondary motion transmitter.

121. In a device as described, in combination, a pitcher positioner, a pitcher tilter, said tilter moving with said positioner, a color-car, and means controlled by said color-car, and adapted to actuate said 95 pitcher tilter.

122. In a device as described, in combination, a pitcher positioner, means carried by said positioner for tilting said positioner, and means for automatically increasing the 100 tilt of said pitcher positioner.

123. In a device as described, in combination, a pitcher positioner, means carried by said positioner adapted to tilt the pitcher, and means independent of said positioner 105 adapted to increase the tilt of said pitcher.

124. In a device as described, in combination, a pitcher positioner, a pitcher tilter, and means for increasing the tilt of said pitcher, automatically step by step.

125. In a device as described, in combination, a pitcher positioner, means for tilting said pitcher, a pitcher tilt increaser, and means for simultaneously actuating said pitcher positioner and said tilting means.

126. In a device as described, in combination, a pitcher positioner, means for tilting the pitcher, means co-operating with the other means for increasing the tilt of said pitcher, and means for automatically and simultaneously actuating the other two means.

127. In a device as described, in combination, a pitcher carrier, tilting mechanism for the pitcher movable with said carrier, mechanism increasing the tilt of said pitcher periodically, a color-car, means controlled by said color-car for actuating said positioner and tilting mechanism, and means controlled in time with said tilting mech- 125 130

anism for actuating said tilt increasing mechanism.

128. In a device as described, in combination, a color-car, means for positioning said color-car, a pitcher holding device, means for positioning said pitcher holding device over the color-car, and a common actuator for both positioners.

129. In a device as described, in combination, a color-car, means for moving said color-car, a pitcher holding device, means for moving said pitcher holding device, a continuously rotating shaft, means controlled by said shaft for actuating said color-car, and 15 means also controlled by said shaft for actuating said pitcher holder moving means.

130. In device as described, in combination, a receptacle, check controlled means for moving said receptacle, and automatic 20 means for emptying said receptacle.

131. In a device as described, in combination, a receptacle, means for supporting said receptacle, check controlled means for moving said receptacle and automatic means for 25 actuating said receptacle.

132. In a device as described, in combination, a receptacle, means for supporting said receptacle, check controlled means for moving said receptacle, automatic means for actuating said means, and automatic means for upsetting said receptacle.

133. In a device as described, in combination, a vessel support, a tilter therefor, and a tilt indicator.

134. In a device as described, in combination, a vessel support, a tilter therefor, means for actuating said tilter, a tilt indicator, and means for actuating said tilt indicator.

135. In a device as described, in combination, a vessel support, means for tilting said vessel, means for registering the number of tilts, and means for automatically actuating said last-named means.

136. In a device as described, in combination, a vessel support, means for tilting said vessel carried by said support, a tilt register, and means for selectively and automatically actuating said tilt register.

137. In a device as described, in combination, a vessel support, color transfer mechanism controlled therewith, and an indicator for said color transfer mechanism.

138. In a device as described, in combination, a vessel support, color transfer mechanism, a tilter therefor, a tilt register and means controlled by said register for actuating said color transfer mechanism.

139. In a device as described, in combination, a vessel support, means for tilting said vessel, and automatic means for regulating the angle of tilt.

140. In a device as described, in combination, a vessel support, means for tilting said vessel, and means for automatically increasing said tilt.

141. In a device as described, in combination, a vessel support, means for tilting said vessel, means for regulating the angle of tilt, and automatic means timing the operation of both of the other means.

70

142. In a device as described, in combination, a vessel support, means for tilting said vessel, a tilt regulator, and means for automatically timing said tilt regulator.

75

143. In a device as described, in combination, a vessel support, means for tilting said vessel, a tilt regulator, means for automatically setting said regulator and means for automatically resetting said regulator.

144. In a device as described, in combination, a vessel support, and automatic means for angularly positioning said support.

80

145. In a device as described, in combination, a vessel support, means for automatically and angularly positioning said vessel, and means for changing the angle of tilt successively.

85

146. In a device as described, in combination, a movably supported vessel, means for tilting said vessel, a tilt increaser, and means for selectively controlling said tilt increaser.

90

147. In a device as described, in combination, a vessel support, means engaging said vessel to turn it, a movement controller for said means, a regulator for said movement controller, and means for automatically and successively actuating said regulator.

95

148. In a device as described, in combination, a vessel support, means engaging said vessel to turn it, a variably shiftable member for actuating said means, a color-car, and means controlled by said color-car and adapted to control said shiftable member.

100

149. In a device as described, in combination, a vessel support, means engaging said vessel to turn it, a variably shiftable member for actuating said means, a regulator for said shiftable member having a graduated movement, and means for automatically actuating said shiftable member.

105

150. In a device as described, in combination, a vessel support, means engaging said vessel to turn it, color-printing mechanism, means controlled by said color printing mechanism for automatically actuating said first-named means.

110

151. In a device as described, in combination, a vessel support, means engaging said vessel to turn it, a cam shaft, means carried by said cam for actuating said means, and means governing the periodicity of actuation of said last-named means.

115

152. In a device as described, in combination, a vessel support, means engaging said vessel to turn it, and means automatically actuating said last-named means for regulating the number of turns.

120

153. In a device as described, in combination, a vessel support, means engaging said vessel to turn it, means controlling the num- 130

ber of vessel turns, and jacquard controlled means for actuating said means.

154. In a device as described, in combination, a vessel support, means engaging said vessel to turn it, an actuator for said means, and automatic jacquard controlled means engaging said actuator to increase the number of tilts of said vessel.

155. In a device as described, in combination, a vessel support, means engaging said vessel to turn it, an actuator for said means, means acting in time with said actuator to make it cause larger turns of said vessel, and jacquard controlled mechanism adapted to 10 actuate said last-named means.

156. In a device as described, in combination, a vessel support, a lever, means whereby said vessel is turned, said lever actuating said means, a device coöperating with said 20 lever and means to govern the vessel's turns, and a tally for said device.

157. In a device as described, in combination, a vessel support, means for tilting said vessel, a tilt increaser, a tally for said tilt 25 increaser, and jacquard controlled mechanism designed to control said tally.

158. In a device as described, in combination, a shaft, a ratchet thereon, a pawl carrying lever, a tensioning device engaging 30 said shaft, said pawl moving said ratchet to turn said shaft against the tension of said device, a vessel tilter, means for successively increasing the tilt of said vessel, an actuator for said means operating at each turn of 35 said ratchet, and means automatically operating said pawl carrying lever.

159. In a device as described, in combination, a shaft, a vessel support, a cam on said shaft, means controlled by said cam for 40 shifting said support, a vessel tilter, means gradually actuating said tilter, an actuator for said means, and means for rendering said actuator inactive.

160. In a device as described, in combination, a shaft, means for intermittently turning said shaft, a cam on said shaft having a gradually increasing throw, a vessel support, means engaged by said cam for imparting increasing tilts to said vessel, and 45 means for automatically restoring said cam to initial position.

161. In a device as described, in combination, a movable vessel holder, a vessel carrying arm, means for swinging said arm over said holder to deliver a vessel thereupon, and means automatically retracting said arm to allow said holder to move to present another vessel, said arm adapted to move to lift said last named vessel.

162. In a device as described, in combination, a vessel carrying arm, having a vessel receiving, a vessel delivering and a neutral position, color printing mechanism, means controlled by said color printing mechanism 60 governing the vessel delivering position of

said arm, and cam controlled means governing the vessel receiving position of said arm.

163. In a device as described, in combination, a vessel support, means for tilting said vessel to pouring position, an actuator for 70 said means having a variable throw, a controller for said actuator having a variable throw, means moving to time the operation of said actuator, and means operated as said mentioned means moves and adapted to 75 actuate said controller.

164. In a device as described, in combination, a vessel tilting mechanism, means whereby said mechanism successively tilts said vessel at greater angles, means automatically restoring said vessel after each angular tilt, a color-car, means controlled by said car for actuating said mechanism, said color car receiving dye holding boxes into which said vessel empties dye, box removing mechanism engageable with said car, and means controlled by said mechanism after its last tilting operation to actuate the 80 last-named mechanism.

165. In a device as described, in combination, vessel tilting mechanism, a rotatable regulator for said mechanism, means turning said regulator in one direction successively, said regulator increasing the tilt of 90 said vessel successively, a tension device opposing the turning of said regulator, and jacquard controlled mechanism adapted to 95 release said means.

166. In a device as described, in combination, a vessel carrier, means initially causing said carrier to obtain a vessel, auxiliary mechanism for hauling said carrier to a final working position, means for tilting said vessel to gradually empty its contents, and means for controlling the initial and working 100 positions of said vessel.

167. In a device as described, in combination, a dye holding vessel support, mechanism imparting to said vessel a plurality of turns to angularly position it gradually, a color-car having a dye holding box replenished at each separate tilt of said vessel, a regulator governing the tilts of said vessel, a box replacer, and automatic means operated by said regulator for actuating said 105 replacer when said vessel has exhausted its tilts.

168. In a device as described, in combination, a shaft, an intermittently actuatable cam thereon, an increasable tilter for a vessel, means controlled by said cam for gradually actuating said tilter, color printing mechanism receiving the contents of said vessel, and means controlled by said mechanism adapted to time the operation of said 110 115 means.

169. In a device as described, in combination, an intermittently actuatable regulator, means for winding said regulator up periodically, a vessel tilter, means controlled 120 125 130

by said regulator adapted to actuate said tilt successively to increase its tilt, a color-car controlling the operation of said first-named means, jacquard controlled mechanism delivering dye-holding boxes to said car, and means controlled by said mechanism for unwinding said regulator.

170. In a device as described, in combination, a box-holding color-car, dye-holding box delivery mechanism therefor, box-filling dye delivering mechanism for the first mechanism means controlled by said car for actuating the second mechanism, and means controlled by the second mechanism controlling the actuation of the first mechanism.

171. In a device as described, in combination, a vessel support, means for initially inclining said vessel, a color-car, means controlled by said color-car for actuating said means, means for successively increasing the inclination of said vessel, means for restoring said vessel to initial position after each initial or successive tilt, and means acting with the last-named means for actuating said vessel inclination increaser for each successive tilt.

172. In a device as described, in combination, a color-car carrying a dye-holding box, color-box change mechanism, color-box dye replenishing mechanism, and means for holding said first-named mechanism inactive as the second named mechanism operates.

173. In a device as described, in combination, a color-car, means for delivering to and removing from said car dye-holding boxes, means for delivering dye to said box, and means whereby said first and second named means may act in timed relation.

174. In a device as described, in combination, a color-car, means for positioning a dye-holding box thereupon, said means also effective to remove said box from said car, means for successively replenishing said box with dye, a register for said last-named means automatically set up step by step to time said last-named means, car-controlled means for actuating said replenishing means, a catch-preventing retrograde movement of said register, and means controlled by the first means for releasing said catch to allow said register to be restored to normal position.

175. In a device as described, in combination, color-printing mechanism, a drum engaged thereby, means for turning said drum periodically, jacquard controlled color-change mechanism coöperating with said color printing mechanism and means for holding said drum against turning as said color change mechanism operates.

176. In a device as described, in combination, a jacquard controlled color-car, a drum engaged thereby, color change mechanism coöperating with said color car, means for

turning said drum as said color car coöperates with said turning means, said color car being stopped as said color change mechanism engages it, and means for automatically stopping said drum as soon as said mechanism operates.

70

177. In a device as described, in combination, a jacquard controlled rotatable drum, a color-car, color change mechanism engageable with said color-car, and means for automatically and simultaneously actuating said mechanism and stopping said drum.

178. In a device as described, in combination, a color-car, means for moving said color-car, jacquard controlled color change mechanism coöperating with said color-car, and means controlled by said first means for stopping said color-car at said color change mechanism.

179. In a device as described, in combination, a cam shaft, a color-car, means carrying a box to said color-car, and means controlled by said cam for actuating said means.

180. In a device as described, in combination, a cam shaft, a color-car, a continuously driving shaft, jacquard controlled means for connecting said shafts for simultaneous rotation, means controlled by said continuously driving shaft for operating said color-car, dye-delivering mechanism for said color-car, and means controlled by said cam shaft for actuating said last-named means.

181. In a device as described, in combination, a color-car, a shaft, jacquard controlled means for turning said shaft, a tongs adapted to carry a color box to said color-car, means adapted to open said tongs to release said box in said car, and means controlled by said shaft adapted to control the operation of said tongs and tongs opening means.

100

182. In a device as described, in combination, a color-car, means for definitely positioning said color-car mechanism delivering dye to said color-car, means for actuating said color-car, means for actuating said mechanism, and means for simultaneously controlling said mechanism and said positioning means.

105

183. In a device as described, in combination, a color-car, means for definitely positioning said color-car, a tongs traveling to deliver a color-box to said car, means for opening said tongs to release a box upon said car, means for actuating said tongs, and unitary means controlling said car positioner, said tongs actuator and said tongs opener.

110

184. In a device as described, in combination, a color-car having a color roll, means for rotating said roll, mechanism for uncoupling said color roll from said means, and jacquard controlled means for actuating said uncoupling mechanism.

125

185. In a device as described, in combina-

- tion, a color-car equipped with yarn scrapers, means for definitely positioning said car, wipers operatively engageable with said scrapers, and means for controlling the actuation of said wipers and said positioning means. 65
186. In a device as described, in combination, a color car having a color roll adapted to be uncoupled, means for definitely positioning said color car, means for uncoupling said color roll, and unitary mechanism adapted to operate said positioner and uncoupling means in turn. 70
187. In a device as described, in combination, a color mechanism, having yarn engaging scrapers, wipers adapted to engage said scrapers, and jacquard controlled means adapted to actuate said wipers. 80
188. In a device as described, in combination, a color-car, means for positioning said car in a determinate position, means holding a plurality of color-boxes, means interposed between said other means and said color car for taking any of said color-boxes and delivering it to said car. 85
189. In a device as described, in combination, a magazine holding a number of color boxes, means adapted to turn said magazine to present fresh color-boxes, color-printing mechanism, and means fed from said magazine for supplying said color printing mechanism with color boxes. 90
190. In a device as described, in combination, a magazine holding a number of color boxes, each color-box having a color roll, means adapted to turn said magazine to present fresh color-boxes, a color car adapted to be positioned adjacent to said magazine, a common releasable actuator for said color rolls, and mechanism adapted to actuate said car positioning means. 95
191. In a device as described, in combination, a magazine holding a number of color boxes, a tongs movable to seize a color-box from said magazine, a color car movable for the purpose of receiving the color box from said tongs, means positioning said car for the last-named purpose, and jacquard controlled mechanism for controlling said magazine, said tongs and said car positioner. 100
192. In a device as described, in combination, a color-car, a drum extending transversely of the path of movement of said car, means opposite one end of said drum for actuating said car, means disposed at the opposite end of said drum for supplying said car with dye, and means for actuating said first means and said second means. 105
193. In a device as described, in combination, a color-car, a drum extending transversely of the path of movement of said color-car, a crank shaft and a cam shaft both located opposite one end of said drum, color change mechanism engaged opposite the far- 110
- ther end of said drum, means for coupling and uncoupling both shafts, jacquard means for actuating the last-named means, means controlled by said crank shaft for moving the color-car and means controlled by said cam shaft controlling said mechanism. 115
194. In a device as described, in combination, a color car, means for moving said color car, a color box carrying tongs normally disposed laterally of the car, and means adapted to swing said tongs over the color-car. 120
195. In a device as described, in combination, a color-car, means for moving said car, color-box carrying tongs normally disposed laterally of said car, and means for swinging said tongs diagonally over said car. 125
196. In a device as described, in combination, a color-car, means for moving said color-car, a color-box holding tongs normally disposed laterally of the car, said tongs adapted to swing in a diagonal path relatively to said color-car to a position over said car, and a cam shaft actuating the swinging of said tongs. 130
197. In a device as described, in combination, a color-car, a magazine having rows of pitchers, means for shifting said magazine transversely of said car, a cam shaft, means controlled by said cam shaft for turning said magazine, and means for actuating the shifting of said magazine. 135
198. In a device as described, in combination, a track, a color-car movable thereon, a magazine having rows of pitcher holders, and means for automatically shifting any of said rows of pitcher holders in line with said car. 140
199. In a device as described, in combination, a color-car, a pitcher carrying device movable in line with said car, a color-box carrying tongs normally disposed laterally of said color-car, means for moving said tongs to a position in line with said color car, means controlled by said car for actuating said device and jacquard controlled means for actuating said tongs. 145
200. In a device as described, in combination, a color-car, a pitcher holding device movable in line with said car, a magazine holding pitchers and movable in line with said device, means for shifting said magazine, and means controlled by said car for actuating said device. 150
201. In a device as described, in combination, a color-car, a crank shaft, means controlled by said crank shaft for moving said color car, a cam shaft, intercoupleable gears on both shafts, jacquard controlled means for effecting the coupling of said gears, color change mechanism, and means controlled by said cam shaft for actuating said mechanism. 155
202. In a device as described, in combina-

- tion, color-printing mechanism, a magazine holding a series of color-boxes, and pitchers, the pitchers being alongside said color-boxes, means movable toward said magazine to obtain a pitcher, means movable alongside said magazine to obtain a color-box, and means for automatically and simultaneously actuating both means. 203. In a device as described, in combination, a color-car, a magazine containing color boxes and pitchers, mechanism supplying boxes from said magazine to said car, mechanism supplying said car with dye of the same color, selective mechanism for predeterminedly actuating said first-named mechanism, said second mechanism also adapted to actuate the first mechanism, and means controlled by said color-car for actuating the second mechanism. 204. In a device as described, in combination, a color-car, a printing drum engaged by said color car, means supplying different colors to said color car interchangeably, means supplying an extra quota of the same color to the color car, means controlled by said color car and engageable by said last-named means for actuating the last-named means, and jacquard controlled means for actuating said first-named means. 205. In a device as described, in combination a color car, a vessel designed to pour dye into said car, car-controlled mechanism controlling the actuation of said vessel, means for automatically repeating the operation of said vessel, and means for automatically replacing the exhausted vessel. 206. In a device as described, in combination, a magazine carrying vessels having a similarly colored dye, a color car, color printing mechanism carried by said car, means conveying any of said vessels from magazine to said car, and jacquard controlled mechanism actuating said means. 207. In a device as described, in combination, a magazine carrying color boxes of different colors, and vessels of the same color for replenishing boxes of these same colors, color printing mechanism receiving color boxes successively, means for simultaneously removing a color box and a vessel of the same color therewith from said magazine, means for transferring the last-named color box to said car, jacquard controlled mechanism controlling the last-named means, and means for transferring the contents of said mentioned vessel into the mentioned color-box automatically. 208. In a device as described, in combination, a magazine containing a plurality of stations, means for controlling the movement of said magazine from one station to another station, a plurality of dye-holding boxes and vessels arranged in each station, a color-car, mechanism capable of simultaneously re-moving a box and vessel from each station alternately, and jacquard controlled means capable of delivering said removed box to said car. 209. In a device as described, in combination, a magazine containing a plurality of stations, each station containing a series of conforming members, boxes and pitchers adapted to engage said members in alining relation in all the stations, the pitchers adapted to be alongside the boxes, means for moving said magazine from one station to another station, and means for automatically shifting said magazine from one set of boxes and pitchers to another set of boxes and pitchers. 210. In a device as described, in combination, a printing drum, a jacquard controlled index, means controlled by said index for actuating said printing drum, a color car movable into engagement with said printing drum, said color car adapted to move beyond said printing drum, a feeler engaged by said car, dye-delivering mechanism, and means controlled by the engagement of said car and feeler for actuating said mechanism. 211. In a device as described, in combination, a printing drum, a jacquard controlled index operating said drum, a magazine holding dye vessels, dye-delivering mechanism associated with said magazine, a dye feeler, a color car engageable with said drum and with said feeler, and means controlled by said feeler for actuating said mechanism. 212. In a device as described, in combination, a drum, a color car, a crank shaft actuating said car, jacquard-controlled means for actuating said drum, color box delivery mechanism for said color car, color-box replenishing means, a constantly operating element on said shaft for timing the operation of said mechanism, a constantly operating element on said shaft for timing the operation of said color-box replenishing means, means actuating said delivery mechanism controlled by the first element and means actuating said replenishing means controlled by the second element. 213. In a device as described, in combination, a magazine having spaced apart shelves containing dye holding vessels in rows, the vessels on the respective shelves being in alinement row by row, means for moving said magazine consecutively from shelf to shelf to present the alining vessel of each row successively, and jacquard controlled means for actuating said last-named means. 214. In a device as described, in combination, a magazine holding vessel containing dye, said magazine having a series of movable stations, jacquard controlled mechanism moving said magazine from one station to another station, successively, a series of sub-

- stations dividing each station longitudinally, and means controlled by said mechanism designed to move said magazine a distance equal to that between two sub-stations automatically.
215. In a device as described, in combination, a magazine having a series of radially disposed stations, means for periodically moving said magazine station by station, each station being longitudinally divided into a series of sub-stations, means registering the moves of said magazine station by station, and means controlled by the last-named means adapted to move said magazine longitudinally sub-station by sub-station automatically.
216. In a device as described, in combination, a magazine having radially extending arms, shelves carried by said arms, jacquard controlled means for turning said magazine, and means for maintaining said shelves in horizontal position as said magazine turns.
217. In a device as described, in combination, a magazine having radially extending arms, elongated shelves mounted upon said arms, said magazine adapted to hold dye-containing vessels, vessel delivering mechanism stationed adjacent said magazine, means for periodically and successively positioning each shelf opposite said mechanism, automatic means for moving said magazine longitudinally, an actuator for said last-named movement of the magazine, and means controlled by said magazine, as it turns, for operating said actuator.
218. In a device as described, in combination, a color-car, means for guiding said color-car, means for actuating said color-car, a primary and a secondary cut-out for said color-car, a yarn cylinder, jacquard controlled means for turning said cylinder, said means also controlling said primary cut-out, and means for actuating said secondary color cut-out.
219. In combination, color-printing mechanism, color change mechanism supplying said other mechanism with color-dye, jacquard controlled means actuating each mechanism separately, and means for restraining the operation of said printing mechanism to allow said color change mechanism to operate.
220. In a device as described, in combination, a support, a lever pivotally connected to said support at its upper end, a box gripping means carried by said lever, a releaser for said means, and jacquard controlled means for actuating said releaser.
221. In a device as described, in combination, a color-car, means for moving said color car, means engageable with said first means to actuate the latter, a shiftable starter for said last-named means, color change mechanism, and means controlled by
- said mechanism adapted to actuate said 65 starter.
222. In a device as described, in combination, a color car, a power transmission mechanism, means controlled by said mechanism for effecting the movement of said car, 70 means controlled by said mechanism for cutting out the movement of said car, color change mechanism, jacquard mechanism for actuating said color change mechanism, and means controlled by said color change 75 mechanism for cutting out the operation of said color car.
223. In a device as described, in combination, a color-car, color change mechanism, an index wheel, means controlled by said index 80 wheel for actuating said color car, a color car cut out mechanism, means controlled by said index wheel for operating said mechanism, means controlled in time with said color change mechanism adapted to render 85 said index wheel inactive, and means controlled by said color change mechanism adapted to actuate said color car cut out when said index wheel is inactive.
224. In a device as described, in combination, a color car, an index wheel, means controlled by said index wheel for effecting the movement of said color car, color transfer mechanism, a color car cut out controlled by said index wheel, another color car cut out, 95 and means for automatically rendering one color car cut out active and the other color car cut out inactive.
225. In a device as described, in combination, a yarn holder, a color-printing mechanism, pattern mechanism controlling said mechanism, means for changing the color in said color printing mechanism, and means to control said mechanism independently of said pattern mechanism.
226. In a device as described, in combination, a color car, means for moving said color car, color transfer mechanism supplying said color car with color dye, means for stopping the motion of said color car, means for cutting out said car stopping means, a detent controlling both of the last-named means, a pusher engageable with said detent to operate it, and means controlled by said mechanism adapted to actuate said pusher.
227. In a device as described, in combination, a source of color box supply, a box receiving member movable adjacent said source, a box gripping member interposed between said box receiving member and said source, jacquard controlled means for moving said box gripping member to cause it to obtain a box from the source, swing it away therefrom, deposit it upon said member and then swing back again, and means for rendering said last-named means inactive.
228. In a device as described, in combination, a magazine holding a supply of color

boxes, a color car, means for periodically turning said magazine to present fresh color boxes, a box carrying device, means for moving said device over said color car to obtain 5 a box therefrom and to swing said device back again to cause said device to present said box upon said magazine, said device swinging out of contact with said magazine to allow the latter to turn, and means 10 operating with the last-named means and designed to cause said device to get a fresh box from said magazine and deposit it upon said member.

229. In a device as described, in combination, a pitcher grasping means, a pitcher release means, a common actuator for either of said means, and jacquard controlled means for actuating said actuator.

230. In a device as described, in combination, pitcher grasping means, a pitcher release means, a pitcher tilting means and a common support for all of said means.

231. In a device as described, in combination, a pitcher grasping means, pitcher release means, a pitcher tilter, means for actuating said grasping means, and means controlled by the last-named means for actuating said pitcher release means, means for actuating said pitcher tilter, and jacquard 30 means for operating said first and second-named actuating means.

232. In a device as described, in combination, means for grasping and supporting a pitcher, means associated with the first means 35 for releasing its pitcher support, color printing mechanism, means controlling said mechanism and designed to actuate the first-named means and means acting in time with said mechanism for actuating said releasing 40 means.

233. In a device as described, in combination, a pitcher grasping device, a carrier movably supporting said device, means for tilting said device automatically as said carrier moves, color printing mechanism, and means controlled by said mechanism designed to automatically actuate said carrier.

234. In a device as described, in combination, a pitcher grasping device, means for 50 opening and closing said device, means for supporting said device, means for positioning the last-named means, jacquard controlled means for actuating said first-named means, color printing mechanism coöperating with said first-named means, and means controlled by said mechanism adapted to actuate said positioning means.

235. In a device as described, in combination, a swinging arm, a pitcher grasping device carried by said arm, means for opening and closing said device, and a dismantlable movable member adapted to actuate said last-named means.

236. In a device as described, in combination, a movable support, a cage carried at

the upper end of said support, means for opening and closing said cage, a reciprocatable actuator for said last-named means, means for moving said support away from said actuator and jacquard controlled means 70 adapted to control said reciprocatable actuator.

237. In a device as described, in combination, a movable support, pitcher grasping means carried by said support, said means 75 consisting of an under support for a pitcher and side supports therefor, means for automatically retracting said supports from a pitcher, and means for automatically actuating either said grasping or said retracting means.

238. In a device as described, in combination, a movable support, a pitcher grasping device carried by said support, said grasping device consisting of an under 85 support and side supports for a pitcher, means for connecting said supports for unison movement, a self-locking means associated with said connecting means, and mechanism for automatically actuating said 90 connecting means.

239. In a device as described, in combination, a movable support, a pitcher grasping device carried by said arm and consisting of an under support and side supports for a 95 pitcher, said supports being interconnected for joint-movement, means for pushing said interconnected supports for joint operative action, and means for automatically locking said interconnected supports upon the 100 actuation of said pushing means.

240. In a device as described, in combination, a support, a pitcher grasping device, mounted on said support, said pitcher grasping device consisting of an under support for 105 a pitcher and side supports therefor, a spring movably separating said supports in open position, a latch carried by said device, and means closing said supports against said pitcher and acting to latch said supports in 110 this position against the tension of said spring.

241. In a device as described, in combination, a track, a color car movable over said track, a color roll in said color car, a yarn-holding cylinder, said roll contacting said cylinder as said color car passes thereunder, and means for automatically causing said roll to duck said cylinder as said car passes thereunder.

242. In a device as described, in combination, a track, a color car movable upon said track, a vertically yieldable printing roll carried by said car, a yarn cylinder, means for moving said car under said cylinder 125 whereby to allow contact of its roll with said cylinder, and jacquard controlled means for positioning said roll whereby it will be out of contact with said cylinder.

243. In a device as described, in combina- 130

- tion, a track, a color car movable upon said track, a vertically movable frame carried by said car, a printing roll on said frame, a yarn cylinder, said frame normally holding said roll so that the latter contacts with the cylinder, and jacquard controlled means for automatically locking said frame in a position where said roll may be out of contact with said cylinder.
- 10 244. In a device as described, in combination, a track, a jacquard controlled color car movable upon said track, a yarn-holding cylinder, a movable roll carried by said car, means for effecting contact between said roll and said cylinder, and means for automatically holding said roll out of contact with said cylinder.
- 20 245. In a device as described, in combination, a color car, color printing mechanism, color-change mechanism, said color car adapted to actuate said color printing mechanism, an impression making element carried by said color printing mechanism having an active and an inactive position, and 25 means controlled by said color change mechanism and adapted to move said element into inactive position.
- 30 246. In a device as described, in combination, a color car, a printing roll carried by said color car, a movable yarn holding cylinder, means for automatically stopping the rotation of said cylinder, means for holding said roll in a position to contact said cylinder, and means acting in time with said last-named means for retracting said roll from contact with said cylinder.
- 40 247. In a device as described, in combination, a color car, a printing roll carried by said color car, a yarn cylinder, means for reciprocating said car under said cylinder and beyond opposite ends thereof, a printing element carried by said color car movably contacting said cylinder, and mechanism designed to cause said printing roll to 45 duck said cylinder when said car is moving in one direction only.
- 50 248. In a device as described, in combination, color printing mechanism, color dye supply mechanism, means for operating said color printing mechanism, means for engaging said mechanisms together, and means for rendering said color-printing mechanism inactive as said mechanisms interengage.
- 55 249. In a device as described, in combination, color printing mechanism, color dye supply mechanism, said printing mechanism having an impression making element, means whereby said element is operated as it leaves said dye supply mechanism, and means 60 whereby said impression making element is rendered inactive as it moves toward said dye-supply mechanism to engage with the latter.
- 65 250. In combination mechanism adapted to form yarn into coils, and automatic means for printing color impressions of two or more colors on said coils.
251. In combination, mechanism adapted to form yarn into bights, printing mechanism adapted to make color impressions on 70 said bights, and automatic means for changing the color in said printing mechanism.
252. In combination, means adapted to support yarn arranged in bights, printing mechanism adapted to make color-dye impressions on said bights, and automatic means for changing the dye in said mechanism.
253. In combination, means adapted to support yarn arranged in bights, printing 75 mechanism adapted to make color dye impressions on said bights, and automatic jacquard controlled means for successively determining the color of the dye used for said impressions.
254. In combination, means adapted to support yarn arranged in coils, printing mechanism adapted to make color-dye impressions on said coils, and automatic means for changing the dye in said mechanism.
255. In combination, mechanism adapted to form yarn into coils, printing mechanism adapted to make color-dye impressions of two or more colors, and automatic means for causing contact between said coils and said printing mechanism.
256. In combination, means adapted to hold yarn in coils, printing mechanism adapted to make color-dye impressions of two or more colors, and automatic means for effecting contact between said coils and said mechanism.
257. In a device as described, in combination, a warp holder, color printing mechanism engageable therewith, means for changing 105 the color in said mechanism, means adapted definitely to alter from point to point the relative positions of said holder and said mechanism, and jacquard controlled means for altering said relative positions intermediate said definite points.
258. In a device as described, in combination, a color car, means for actuating said car, yarn engaging scrapers associated with said car, a color roller carried by said car, means associated with said car for rotating said roller, jacquard mechanism for controlling the stoppage of said first named means and for positioning said car, and mechanism associated therewith for wiping said scrapers and for uncoupling said roller.
259. In a device as described, in combination, a yarn support, color striping mechanism engaging and making impressions on said yarn, jacquard controlled means for 125 changing the color-dye in said mechanism, and automatic mechanism controlling the movements of said striping mechanism during the actuation of said jacquard color change mechanism.

260. In a device as described, in combination, color printing mechanism, a movable magazine adapted to hold color vessels, a color supply receptacle gradually emptied 5 to supply said mechanism with color dye and means operable when said vessel is exhausted for moving said magazine. adapted to change the dye in said mechanism, and means causing the engagement of said member and said color mechanism. 65
261. In a device as described, in combination, means for variably positioning a yarn 10 support at predetermined color impression positions, color printing mechanism adapted to operatively engage said support and means for supplying color to said mechanism while said support is being positioned. 270. In a device as described, in combination, a color car, means for actuating said car, and jacquard controlled mechanism for 70 positioning said car.
- 15 262. In a device as described, in combination, a movable magazine adapted to hold color vessels and jacquard controlled means for moving said magazine. 271. In a printing drum in combination jacquard mechanism controlling the actuation of the following instrumentalities, the 75 yarn support, color-applying mechanism, color change mechanism, pitcher carrier mechanism, and color-dye magazine.
- 20 263. In a device as described, in combination, yarn printing mechanism, a magazine adapted to hold color dye for said mechanism and jacquard controlled means for 80 positioning said magazine. 272. In a device as described, in combination, a movable yarn holder, a color printing device operably engageable with said 85 holder, means for changing the color in said device, means operative to move said holder to definite stop positions and jacquard controlled means operable to position said holder intermediate said definite stop positions.
- 25 264. In a device as described, in combination, a yarn carrier, a color mechanism adapted to make color impressions on said carrier, a device adapted to gage the amount of color used by said mechanism, and means for nullifying said device. 273. In a device as described, in combination, a color printing mechanism, a yarn support operably adapted to repeatedly pass by said color printing mechanism, means 90 for engaging said support and said mechanism, and jacquard controlled means for changing the color in said mechanism.
- 30 265. In a device as described, in combination, a yarn carrier, color mechanism adapted to make color impressions on said carrier, a device adapted to measure the amount of color in said mechanism, and means operable to keep said device from measuring said 95 amount of color. 274. In a device as described, in combination, a yarn holder, a color printing mechanism operable to contact said holder, pattern controlled means governing the moves of said mechanism, and means operable to keep said mechanism from contacting said holder during a movement of said mechanism. 100
- 35 266. In a device as described, in combination, a yarn carrier, color mechanism adapted to make color impressions on said carrier, an element indicating the amount of color dye in said mechanism, and a register operable when a determinate amount of color-dye is indicated by said element. 275. In a printing drum, in combination, jacquard mechanism controlling the actuation of the following instrumentalities, a 105 yarn support, a color-applying mechanism, and a device for changing the color in said mechanism.
- 40 267. In a device as described, in combination, a color-car, a color box carried by said car, a feeler adapted to register the position of a float in said box, and a false float 110 engageable with said feeler. 276. In a device as described, in combination, a yarn support, color-impression mechanism operable to engage the yarn on said support, means for varying the distance between identical color impressions made during successive units of time, means to change the color-dye in said mechanism, and jacquard mechanism controlling the actuation of said first and second means. 115
- 45 268. In a device as described, in combination, a member adapted to support a warp unit, jacquard controlled color mechanism acting in cycles and adapted to color the warp on said member at equal intervals throughout its length during each cycle, jacquard controlled color change mechanism 120 adapted to change the dye in said mechanism, and means causing the engagement of said member and said color mechanism. 277. In a device as described, in combination, a yarn support, color impression mechanism to engage the yarn on said support, means acting in cycles to effect contact between said yarn and said mechanism, means for varying the distance between identical color impressions made during successive cycles, means to change the color-dye in said mechanism, and jacquard mechanism controlling the actuation of said first, second 125 and third means.
- 50 269. In a device as described, in combination, a member adapted to support a warp unit, color mechanism acting in cycles and adapted to color the warp on said member at equal intervals throughout its length during each cycle, color change mechanism 130

nism, color applying mechanism adapted to color the yarn on said support while stroking toward or away from said color change mechanism and means for stroking said 5 color applying mechanism without coloring said yarn.

279. In a device of the class described,

the combination of a color printing mechanism, a printing element associated therewith, and pattern controlled means operable 10 to disassociate said element from said mechanism.

CLINTON ALVORD.
